DEVELOPING DEVICE

FIELD OF THE INVENTION AND RELATED ART

The present invention relates to a developing device for developing an electrostatic latent image, formed on an image bearing member, with a developer.

As the developing device, a constitution in which two developing rollers for developing the electrostatic latent image, formed on the image bearing member, with the developer are arranged side by side with respect to a rotational direction of the image bearing member is proposed (United States Patent Application Publication No. 2013/0330107). In the developing device disclosed in US2013/0330107 A1, of the two developing rollers, to a first developing roller positioned at a lower portion in the vertical direction, the developer is supplied from a supplying portion, and to a second developing roller positioned at an upper portion in the vertical direction, the developer is delivered from the first developing roller positioned at the lower portion.

As described in US2013/0330107 A1, in the case where the developer is delivered from the first developing roller to the second developing roller positioned at the upper portion in the vertical direction, delivery of the developer is made by a magnetic field formed between a delivering pole of a first magnet provided in the first developing roller and a receiving pole of a second magnet provided in the second developing roller. The delivering pole is opposite in polarity to the receiving pole. In such a constitution, when a rotational direction of the second developing roller is opposite to a rotational direction of the first developing roller in a position where the second developing roller opposes the first developing roller, a first magnetic pole adjacent to the delivering pole on a side upstream of the delivering pole is opposite in polarity to a second magnetic pole adjacent to the receiving pole on a side downstream of the receiving pole. For this reason, between the first magnetic pole and the second magnetic pole, a magnetic field for attracting the developer to each of the rollers is generated.

Thus, when the magnetic field for attracting the developer is generated between the first magnetic pole and the second magnetic pole, there is a liability that movement of the developer is generated between the first magnetic pole and the second magnetic pole by this magnetic field. Further, when the developer movement is generated between the first magnetic pole and the second magnetic pole, there is a liability that the moving developer floats and then is deposited on an image bearing member positioned in the neighborhood of the first developing roller and the second developing roller. Thus, when the developer is deposited on the image bearing member, an image defect such as a fog in a vertical stripe shape occurs on an output image.

SUMMARY OF THE INVENTION

A principal object of the present invention is to provide a developing device capable of suppressing an occurrence of an image defect.

According to an aspect of the present invention, there is provided a developing device comprising: a developing container configured to accommodate a developer including toner and a carrier; a first rotatable member to which the developer accommodated in the developing container is supplied and which carries and feeds the developer to a first developing position where an electrostatic latent image

2

formed on an image bearing member is developed; a first magnet provided non-rotatably and stationarily inside the first rotatable member, wherein the first magnet includes a first developing pole provided opposed to the image bearing member in the first developing position, a delivering pole provided downstream of the first developing pole with respect to a rotational direction of the first rotatable member, and a first feeding pole provided upstream of the delivering pole and adjacent to the delivering pole, with respect to the rotational direction of the first rotatable member, and having a magnetic polarity different from the delivering pole; a second rotatable member provided opposed to the first rotatable member and to which the developer is delivered from the first rotatable member by a magnetic field generated by the first magnet, wherein the second rotatable member carries and feeds the developer to a second developing position where the electrostatic latent image is developed, and wherein a rotational direction of the second rotatable member in a position where on an outer peripheral surface of the second rotatable member, the second rotatable member closest to the first rotatable member is opposite to the rotational direction of the first rotatable member in a position where on an outer peripheral surface of the first rotatable member, the first rotatable member is closest to the second rotatable member; and a second magnet provided non-rotatably and stationarily inside the second rotatable member, wherein the second magnet includes a plurality of magnetic poles including a second developing pole provided opposed to the image bearing member in the second developing position, a receiving pole provided upstream of the second developing pole with respect to the rotational direction of the second rotatable member and having a magnetic polarity different from that of the delivering pole, and a second feeding pole provided downstream of the receiving pole and adjacent to the receiving pole, with respect to the rotational direction of the second rotatable member, and having a magnetic polarity different from that of the receiving pole, the receiving pole being a magnetic pole, of the plurality of magnetic poles, provided closest to the delivering pole, wherein in a case where on the outer peripheral surface of the first rotatable member, a magnetic flux density of the delivering pole in a normal direction relative to the outer peripheral surface of the first rotatable member is maximum is a point T, of positions each where on the outer peripheral surface of the first rotatable member, the magnetic flux density of the delivering pole in the normal direction relative to the outer peripheral surface of the first rotatable member is a half value of the maximum, the position on a downstream side with respect to the rotational direction of the first rotatable member is a point Hd, of the positions each where on the outer peripheral surface of the first rotatable member, the magnetic flux density of the delivering pole in the normal direction relative to the outer peripheral surface of the first rotatable member is the half value of the maximum, the position on an upstream side with respect to the rotational direction of the first rotatable member is point Hu, an angle formed by a rectilinear line L10 connecting a rotation center R1 of the first rotatable member and the point T and by a rectilinear line L12 connecting the rotation center R1 and the point Hu is w1, and an angle formed by the rectilinear line L10 and a rectilinear line L11 connecting the rotation center R1 and the point Hd is w2, the following relationship is satisfied: w1-w2≥0. According to another aspect of the present invention, there is provided a developing device comprising: a developing container configured to accommodate a developer

including toner and a carrier; a first rotatable member to which the developer accommodated in the developing container is supplied and which carries and feeds the developer to a first developing position where an electrostatic latent image formed on an image bearing member is developed; a first magnet provided non-rotatably and stationarily inside the first rotatable member, wherein the first magnet includes a first developing pole provided opposed to the image bearing member in the first developing position, a delivering pole provided downstream of the first developing pole with respect to a rotational direction of the first rotatable member, and a first feeding pole provided upstream of the delivering pole and adjacent to the delivering pole, with respect to the rotational direction of the first rotatable member, and having a magnetic polarity different from the delivering pole; a second rotatable member provided opposed to the first rotatable member and to which the developer is delivered from the first rotatable member by a magnetic field generated by the first magnet, wherein the second rotatable member carries and feeds the developer to a second developing position where the electrostatic latent image is developed, and wherein a rotational direction of the second rotatable member in a position where on an outer peripheral surface of the second rotatable member, the second rotatable member closest to the first rotatable member is opposite to the rotational direction of the first rotatable member in a position where on an outer peripheral surface of the first rotatable member, the first rotatable member is closest to the second rotatable member; and a second magnet provided non-rotatably and stationarily inside the second rotatable member, wherein the second magnet includes a plurality of magnetic poles including a second developing pole provided opposed to the image bearing member in the second developing position, a receiving pole provided upstream of the second developing pole with respect to the rotational direction of the second rotatable member and having a magnetic polarity different from that of the delivering pole, and a second feeding pole provided downstream of the receiving pole and adjacent to the receiving pole, with respect to the rotational direction of the second rotatable member, and having a magnetic polarity different from that of the receiving pole, the receiving pole being a magnetic pole, of the plurality of magnetic poles, provided closest to the delivering pole, wherein in a case where a position where on the outer peripheral surface of the first rotatable member, a magnetic flux density of the delivering pole in a normal direction relative to the outer peripheral surface of the first rotatable member is maximum is a point T, of positions each where on the outer peripheral surface of the first rotatable member, the magnetic flux density of the delivering pole in the normal direction relative to the outer peripheral surface of the first rotatable member is a half value of the maximum, the position on a downstream side with respect to the rotational direction of the first rotatable member is a point Hd, and of the positions each where on the outer peripheral surface of the first rotatable member, the magnetic flux density of the delivering pole in the normal direction relative to the outer peripheral surface of the first rotatable member is the half value of the maximum, the position on an upstream side with respect to the rotational direction of the first rotatable member is point Hu, and wherein in a graph in which an ordinate represents the magnetic flux density of the delivering pole in the normal direction relative to the outer peripheral surface of the first rotatable member and an abscissa represents an angle of the first rotatable member with respect to the rotational direction of the first rotatable member, in a case where a rectilinear line passing through

the point T and parallel to the abscissa is a rectilinear line HLt, a rectilinear line passing through the points Hu and Hd and parallel to the abscissa is HLh, a rectilinear line passing through the point Hd and parallel to the ordinate is VL11, a rectilinear line passing through the point Hu and parallel to the ordinate is VL12, an area of a rectangle enclosed by the rectilinear lines VL11, VL12, HLt, and HLh is an area S, and in a region of the rectangle, an area obtained by integrating the magnetic flux density of the delivering pole, in the normal direction relative to the outer peripheral surface of the first rotatable member, from the rectilinear line VL11 to the rectilinear line VL12 in terms of the angle of the first rotatable member with respect to the rotational direction of the first rotatable member is an area Sa, the following relationship is satisfied: $Sa/S \geq 75\%$.

According to a further aspect of the present invention, there is provided a developing device comprising: a developing container configured to accommodate a developer including toner and a carrier; a first rotatable member to which the developer accommodated in the developing container is supplied and which carries and feeds the developer to a first developing position where an electrostatic latent image formed on an image bearing member is developed; a first magnet provided non-rotatably and stationarily inside the first rotatable member, wherein the first magnet includes a first developing pole provided opposed to the image bearing member in the first developing position, a delivering pole provided downstream of the first developing pole with respect to a rotational direction of the first rotatable member, and a first feeding pole provided upstream of the delivering pole and adjacent to the delivering pole, with respect to the rotational direction of the first rotatable member, and having a magnetic polarity different from the delivering pole; a second rotatable member provided opposed to the first rotatable member and to which the developer is delivered from the first rotatable member by a magnetic field generated by the first magnet, wherein the second rotatable member carries and feeds the developer to a second developing position where the electrostatic latent image is developed, and wherein a rotational direction of the second rotatable member in a position where on an outer peripheral surface of the second rotatable member, the second rotatable member closest to the first rotatable member is opposite to the rotational direction of the first rotatable member in a position where on an outer peripheral surface of the first rotatable member, the first rotatable member is closest to the second rotatable member; and a second magnet provided non-rotatably and stationarily inside the second rotatable member, wherein the second magnet includes a plurality of magnetic poles including a second developing pole provided opposed to the image bearing member in the second developing position, a receiving pole provided upstream of the second developing pole with respect to the rotational direction of the second rotatable member and having a magnetic polarity different from that of the delivering pole, and a second feeding pole provided downstream of the receiving pole and adjacent to the receiving pole, with respect to the rotational direction of the second rotatable member, and having a magnetic polarity different from that of the receiving pole, the receiving pole being a magnetic pole, of the plurality of magnetic poles, provided closest to the delivering pole, wherein in a case where a position where on the outer peripheral surface of the first rotatable member, a magnetic flux density of the delivering pole in a normal direction relative to the outer peripheral surface of the first rotatable member is maximum is a point T, of positions each where on the outer peripheral surface of the first rotatable member, the magnetic flux density of the delivering pole in the normal direction relative to the outer peripheral surface of the first rotatable member is a half value of the maximum, the position on a downstream side with respect to the rotational direction of the first rotatable member is a point Hd, and of the positions each where on the outer peripheral surface of the first rotatable member, the magnetic flux density of the delivering pole in the normal direction relative to the outer peripheral surface of the first rotatable member is the half value of the maximum, the position on an upstream side with respect to the rotational direction of the first rotatable member is point Hu, and wherein in a graph in which an ordinate represents the magnetic flux density of the delivering pole in the normal direction relative to the outer peripheral surface of the first rotatable member and an abscissa represents an angle of the first rotatable member with respect to the rotational direction of the first rotatable member, in a case where a rectilinear line passing through

member, the magnetic flux density of the delivering pole in the normal direction relative to the outer peripheral surface of the first rotatable member is a half value of the maximum, the position on a downstream side with respect to the rotational direction of the first rotatable member is a point Hd, and of the positions each where on the outer peripheral surface of the first rotatable member, the magnetic flux density of the delivering pole in the normal direction relative to the outer peripheral surface of the first rotatable member is the half value of the maximum, the position on an upstream side with respect to the rotational direction of the first rotatable member is point Hu, and wherein in a graph in which an ordinate represents the magnetic flux density of the delivering pole in the normal direction relative to the outer peripheral surface of the first rotatable member and an abscissa represents an angle of the first rotatable member with respect to the rotational direction of the first rotatable member, in a case where of positions each where the magnetic flux density of the delivering pole in the normal direction relative to the outer peripheral surface of the first rotatable member is a value which is 10% of the maximum of the magnetic flux density of the delivering pole in the normal direction relative to the outer peripheral surface of the first rotatable member, the position on an upstream side with respect to the rotational direction of the first rotatable member is a point Cu, of positions each where the magnetic flux density of the delivering pole in the normal direction relative to the outer peripheral surface of the first rotatable member is a value which is 10% of the maximum of the magnetic flux density of the delivering pole in the normal direction relative to the outer peripheral surface of the first rotatable member, the position on a downstream side with respect to the rotational direction of the first rotatable member is a point Cd, of positions each where the magnetic flux density of the delivering pole in the normal direction relative to the outer peripheral surface of the first rotatable member is a value which is 90% of the maximum of the magnetic flux density of the delivering pole in the normal direction relative to the outer peripheral surface of the first rotatable member, the position on an upstream side with respect to the rotational direction of the first rotatable member is a point Cu, of positions each where the magnetic flux density of the delivering pole in the normal direction relative to the outer peripheral surface of the first rotatable member is a value which is 90% of the maximum of the magnetic flux density of the delivering pole in the normal direction relative to the outer peripheral surface of the first rotatable member, the position on a downstream side with respect to the rotational direction of the first rotatable member is a point Cd, an angle formed by a rectilinear line L11C connecting the rotation center R1 and the point Cd and a rectilinear line L12C connecting the rotation center R1 and the point Cu is Wc, and an angle formed by a rectilinear line L11D connecting the rotation center R1 and the point Dd and a rectilinear line L12D connecting the rotation center R1 and the point Du is Wd, and the following relationship is satisfied:

$$Wd/Wc \geq 45\%.$$

Further features of the present invention will become apparent from the following description of exemplary embodiments with reference to the attached drawings.

BRIEF DESCRIPTION OF THE DRAWINGS

FIG. 1 is a schematic sectional view of an image forming apparatus in a first embodiment.

FIG. 2 is a schematic sectional view of a developing device according to the first embodiment.

FIG. 3 is a schematic view showing a magnetic pole arrangement of a first developing roller in the first embodiment.

FIG. 4 is a schematic view showing a magnetic pole arrangement of a second developing roller in the first embodiment.

FIG. 5 is a schematic view showing a magnetic pole arrangement of a peeling roller in the first embodiment.

FIG. 6 is a schematic view showing a relationship of a magnetic pole arrangement between the first developing roller and the second developing roller in the first embodiment.

FIG. 15 is a graph showing the magnetic characteristic of the delivering pole of FIG. 14 in an enlarged manner.

FIG. 16 is a graph showing a magnetic characteristic at a periphery of three kinds of delivering poles different in area ratio Sa/S.

FIG. 17 is a graph showing a magnetic characteristic at a periphery of a delivering pole of a first developing roller in a third embodiment.

FIG. 18 is a graph showing the magnetic characteristic of the delivering pole of FIG. 17 in an enlarged manner.

FIG. 19 is a graph showing a magnetic characteristic of a delivering pole of a first developing roller in a fourth embodiment in an enlarged manner.

FIG. 20 is a graph showing a magnetic characteristic of a delivering pole of a first developing roller in a fifth embodiment in an enlarged manner.

DESCRIPTION OF THE EMBODIMENTS

First Embodiment

A first embodiment will be described using FIGS. 1 to 12.

First, a general structure of an image forming apparatus in this embodiment will be described with reference to FIG. 1. [Image Forming Apparatus]

An image forming apparatus 100 is a full-color image forming apparatus, and in the case of this embodiment, the image forming apparatus 100 is, for example, an MFP (multi-function peripheral) having a copy function, a printer function, and a scan function. The image forming apparatus

100 includes, as shown in FIG. 1, image forming portions PY, PM, PC, and PK for performing an image forming step of forming toner images of four colors of yellow, magenta, cyan, and black, respectively, which are juxtaposed.

The image forming portions PY, PM, PC, and PK for the respective colors include primary chargers 21Y, 21M, 21C, and 21K, developing devices 1Y, 1M, 1C, and 1K, optical write portions (exposure devices) 22Y, 22M, 22C, and 22K, photosensitive drums 28Y, 28M, 28C, and 28K, and a cleaning devices 26Y, 26M, 26C, and 26K, respectively. Further, the image forming apparatus 100 includes a transfer device 2 and a fixing device 3. Incidentally, structures of the image forming portions PY, PM, PC, and PK are similar to each other, and therefore, in the following, description will be described using the image forming portion PY as a representative.

The photosensitive drum 28Y as an image bearing member is a photosensitive member, having a photosensitive layer formed of a resin such as polycarbonate, containing an organic photoconductor (OPC), and is constituted so as to be rotated at a predetermined speed. The primary charger 21Y includes a corona discharge pole disposed at a periphery of the photosensitive drum 28Y and electrically charges a surface of the photosensitive drum 28Y by generated ions.

In the optical write portion 22Y, a scanning optical device is assembled, and by exposing the charged photosensitive drum 28Y to light on the basis of image data, a potential of an exposed portion is lowered, so that a charge pattern (electrostatic latent image) corresponding to the image data is formed. The developing device 1Y develops the electrostatic latent image, formed on the photosensitive drum 28Y, by transferring a developer accommodated therein onto the photosensitive drum 28Y. The developer is prepared by mixing a carrier with toner of an associated color, and the electrostatic latent image is visualized (developed) with the toner.

The transfer device 2 includes primary transfer rollers 23Y, 23M, 23C, and 23K, an intermediary transfer belt 24, and a secondary transfer roller 25. The intermediary transfer belt 24 is wound around the primary transfer rollers 23Y, 23M, 23C, and 23K and a plurality of rollers, and is supported so as to be travelable.

The primary transfer rollers 23Y, 23M, 23C, and 23K are disposed in a named order from above in FIG. 1 and correspond to the colors of Y (yellow), M (magenta), C (cyan), and K (black), respectively. The secondary transfer roller 25 is disposed outside the intermediary transfer belt 24 and is constituted so that a recording material is capable of passing through between the secondary transfer roller 25 and the intermediary transfer belt 24. Incidentally, the recording material is a sheet such as paper or a plastic sheet.

The toner images of the respective colors formed on the photosensitive drums 28Y, 28M, 28C, and 28K are successively transferred onto the intermediary transfer belt 24 by the primary transfer rollers 23Y, 23M, 23C, and 23K, respectively, so that a color toner image including superimposed layers of the colors of yellow, magenta, cyan, and black is formed. The thus-formed toner image is transferred by the secondary transfer roller 25 onto the recording material fed from a cassette in which recording materials are accommodated. The recording material on which the toner image is transferred is pressed and heated in the fixing device 3. By this, the toner on the recording material is melted, so that the color image is fixed on the recording material.

Developer storage portions 27Y, 27M, 27C, and 27K are provided correspondingly to the developing devices 1Y, 1M,

1C, and 1K, respectively, and in which bottles accommodating developers corresponding to the colors of yellow, magenta, cyan, and black are exchangeably mounted in a named order from above, respectively. The developer storage portions 27Y, 27M, 27C, and 27K are constituted so that the developers are capable of being fed (supplied) therefrom to the developing devices 1Y, 1M, 1C, and 1K corresponding to the colors of the developers stored therein, respectively.

For example, a toner weight ratio of the developer accommodated in each bottle is 80 to 95%, and a toner weight ratio of the developer in each of the developing devices 1Y, 1M, 1C, and 1K is 5 to 10%. For that reason, when the toner is consumed by development in each of the developing devices 1Y, 1M, 1C, and 1K, the developer containing the toner in an amount corresponding to a consumption amount of the toner is supplied, so that the toner weight ratio of the developer in each of the developing devices 1Y, 1M, 1C, and 1K is maintained in a constant amount.

[Developing Device]

Next, the developing devices 1Y, 1M, 1C, and 1K will be specifically described using FIGS. 2 to 5.

Incidentally, structures of the developing devices 1Y, 1M, 1C, and 1K are the same, and therefore, in the following, the developing device 1Y will be described as a representative. FIG. 2 is a conceptual view illustrating the developing device 1Y shown in FIG. 1, and FIGS. 3 to 5 are conceptual views illustrating magnetic pole structures of a first magnet 36, a second magnet 37, and a third magnet 38 which are provided inside the developing device 1Y, respectively.

The developing device 1Y includes, as shown in FIG. 2, a first developing roller 30, a second developing roller 31, a peeling roller 32, a developer supplying screw 42, a developer stirring screw 43, and a developer collecting screw 44, and these members are accommodated in a developing container 60.

The first developing roller 30 is a developer carrying member which is rotationally driven, and is provided at a position adjacent to the photosensitive drum 28Y so that a rotational axis thereof is substantially parallel to a rotational axis of the photosensitive drum 28Y. The first developing roller 30 includes a first sleeve 33 which is rotatable, and the first magnet (fixed magnet) 36 non-rotationally provided inside the first sleeve 33 and for attracting the developer to a surface of the first sleeve 33 by a magnetic force. Then, the first developing roller 30 attracts (carries) the developer, scooped from the developer supplying screw 42, on the basis of the magnetic force, and develops the electrostatic latent image formed on the rotating photosensitive drum 28Y (image bearing member), with the developer.

The first sleeve 33 is a non-magnetic cylindrical member and is rotationally driven about a rotation shaft 39. A 55 rotational direction of the first sleeve 33 is the clockwise direction as indicated by an arrow in FIG. 2 and is a direction opposite to a rotational direction of the photosensitive drum 28. For this reason, the first sleeve 33 and the photosensitive drum 28Y rotate in the same direction at mutually opposing 60 positions. That is, normal (forward) development such that the photosensitive drum 28 is rotated from below toward above in a vertical direction in the position where the photosensitive drum 28 opposes the first sleeve 33 is performed.

65 The first magnet 36 is disposed inside the first sleeve 33 and includes, as shown in FIG. 3, a plurality of sector magnetic poles 101 to 107. Between an inner periphery of

the first sleeve 33 and an outer periphery of the first magnet 36, a space permitting rotation of the first sleeve 33 is provided.

The developer attracted onto the first sleeve 33 is conveyed toward the photosensitive drum 28Y by a rotation operation of the first sleeve 33, so that the electrostatic latent image formed on the photosensitive drum 28Y is developed with the developer. After the electrostatic latent image formed on the photosensitive drum 28Y is developed with the developer, the developer on the first sleeve 33 is conveyed to the neighborhood of the second developing roller 31 by the rotation operation of the first sleeve 33. Then, in the neighborhood of a closest position between the first developing roller 30 and the second developing roller 31, the developer is peeled off from the first sleeve 33 and then delivered to a surface of a second sleeve 34 by a magnetic field generated by the first magnet 36 included in the first developing roller 30 and by the second magnet 37 included in the second developing roller 31.

The second developing roller 31 is a developer carrying member which is rotationally driven and is provided downstream of the first developing roller 30 with respect to the rotational direction of the photosensitive drum 28Y, and a rotation center R2 of the second developing roller 31 is positioned above a rotation center R1 of the first developing roller 30 with respect to the vertical direction. To the second developing roller 31, the developer is delivered from the first developing roller 30 by the magnetic force (FIG. 2). In this embodiment, entirety of the second developing roller 31 is positioned above the rotation center R1 of the first developing roller 30.

The second developing roller 31 is, similarly as the first developing roller 30, provided at a position adjacent to the photosensitive drum 28Y so that a rotational axis thereof is substantially parallel to a rotational axis of the photosensitive drum 28Y. Accordingly, the second developing roller 31 and the first developing roller 30 are substantially parallel to each other in rotational axis.

Such a second developing roller 31 includes a second sleeve 34 which is rotatable, and the second magnet (fixed magnet) 37 non-rotationally provided inside the second sleeve 34 and for attracting the developer to a surface of the second sleeve 34 by a magnetic force. Then, on the basis of the magnetic force, to the second developing roller 31, the developer is delivered from the first developing roller 30 (the first sleeve 33), and the second developing roller 31 attracts (carries) the developer, and develops the electrostatic latent image formed on the rotating photosensitive drum 28Y, with the developer. Incidentally, on a side of the second developing roller 31, the peeling roller 32 described later is positioned.

The second sleeve 34 is a non-magnetic cylindrical member and is rotationally driven about a rotation shaft 40. A rotational direction of the second sleeve 34 is the clockwise direction as indicated by an arrow in FIG. 2 similarly as the first sleeve 33 and is a direction opposite to a rotational direction of the photosensitive drum 28 in this embodiment. For this reason, the second sleeve 34 and the photosensitive drum 28Y rotate in the same direction at mutually opposing positions. That is, normal development such that the photosensitive drum 28 is rotated from below toward above in the vertical direction in the position where the photosensitive drum 28 opposes the second sleeve 34 is performed. Further, the first sleeve 33 and the second sleeve 34 rotate in opposite directions at mutually opposing positions.

The second magnet 37 is disposed inside the second sleeve 34 and includes, as shown in FIG. 4, a plurality of

sector magnetic poles 201 to 207. Between an inner periphery of the second sleeve 34 and an outer periphery of the second magnet 37, a space permitting rotation of the second sleeve 34 is provided.

The developer attracted onto the second sleeve 34 is conveyed toward the photosensitive drum 28Y by a rotation operation of the second sleeve 34, so that the electrostatic latent image formed on the photosensitive drum 28Y is developed with the developer. After the electrostatic latent image formed on the photosensitive drum 28Y is developed with the developer, the developer remaining on the second sleeve 34 is conveyed to the neighborhood of the peeling roller 32 by the rotation operation of the second sleeve 34. Then, in the neighborhood of a closest position between the second developing roller 31 and the peeling roller 32, the developer is delivered from the second sleeve 34 to a third sleeve 35 of the peeling roller 32 by a magnetic field generated by the second magnet 37 included in the second developing roller 31 and by the third magnet 38 included in the peeling roller 32.

The peeling roller 32 as a peeling portion is provided on a side opposite from the photosensitive drum 28Y with respect to a rotation center of the second sleeve 34 and peels off, from the second developing roller 31, the developer after the electrostatic latent image on the photosensitive drum 28Y is developed by the second developing roller 31. Specifically, the peeling roller 32 is a developer carrying member which is rotationally driven, and is provided between the second developing roller 31 and the developer collecting screw 44 so that a rotation center thereof is positioned above the rotation center R2 of the second developing roller 31.

Further, the peeling roller 32 is disposed so that a rotational axis thereof is substantially parallel to a rotational axis of the second developing roller 31. Such a peeling roller 32 includes a third sleeve 35 which is rotatable, and the third magnet (fixed magnet) 38 non-rotationally provided inside the third sleeve 35 and for attracting the developer to a surface of the third sleeve 35 by a magnetic force, and is constituted so that the developer is delivered from the second developing roller 31 thereto on the basis of the magnetic force.

The third sleeve 35 is a non-magnetic cylindrical member and is rotationally driven about a rotation shaft 41. A rotational direction of the third sleeve 35 is the counter-clockwise direction as indicated by an arrow in FIG. 2 and is a direction opposite to a rotational direction of the second sleeve 34. For this reason, the third sleeve 35 and the second sleeve 34 rotate in the same direction at mutually opposing positions.

The third magnet 38 is disposed inside the third sleeve 35 and includes, as shown in FIG. 5, a plurality of sector magnetic poles 301 to 305. Between an inner periphery of the third sleeve 35 and an outer periphery of the third magnet 38, a space permitting rotation of the third sleeve 35 is provided.

The developer attracted to the third sleeve 35 is conveyed to a downstream side of the rotational direction by a rotation operation of the third sleeve 35 is peeled off from the third sleeve 35 at a position close to the developer collecting screw 44 by the third magnet 38 included in the peeling roller 32, so that the developer is dropped toward a guiding member 45 positioned below with respect to the vertical direction, by a self-weight thereof. Then, the developer dropped on the guiding member 45 is guided toward the developer collecting screw 44 by its own weight.

11

The guiding member 45 and the developer collecting screw 44 constitute a developer collecting portion 47 as a collecting portion for collecting the developer peeled off from the third sleeve 35 on the peeling roller 32. In the developer collecting portion 47, the developer collecting screw 44 is disposed so that a rotation center thereof is positioned below a rotation center of the peeling roller 32 in the vertical direction, and conveys the developer delivered (collected) from the peeling roller 32, while stirring the developer.

The guiding member 45 as a guiding portion is disposed below the peeling roller 32 with respect to the vertical direction, and guides the developer, peeled off by the peeling roller 32, toward the developer collecting screw 44. Such a guiding member 45 is provided with an inclined surface 45a along which the developer slides down by its own weight in order to reliably guide the peeled developer toward the developer collecting screw 44. The inclined surface 45a is inclined with respect to a horizontal direction so that a position thereof on the developer collecting screw 44 side is lower than a lower position of the peeling roller 32.

The developer collecting screw 44 as a collecting member and a conveying (feeding) portion conveys the collected developer to a developer circulating portion 46 described below. That is, the developer collecting screw 44 is a screw conveying (feeding) member used for conveying the developer, collected by being slide down along the inclined surface 45a of the guiding member 45, in one direction while stirring the developer.

The developer circulating portion 46 is a supplying portion for supplying the developer to the first developing roller 30, and includes a regulating member 50, the developer supplying screw 42, and the developer stirring screw 43. In the developer circulating portion 46, the developer is supplied to the first developing roller 30 while the developer is conveyed in the substantially horizontal direction while being stirred in the developer supplying screw 42 and the developer stirring screw 43. Further, as described above, the developer collected by the developer collecting portion 47 is dropped by its own weight and is guided to the developer circulating portion 46.

The developer supplying screw 42, the developer stirring screw 43, and the developer collecting screw 44 are screw conveying members for conveying the developer in one direction while stirring the developer, and the developer supplying screw 42 and the developer stirring screw 43 are positioned below the developer collecting screw 44 with respect to the vertical direction. Further, the developer supplying screw 42, the developer stirring screw 43, and the developer collecting screw 44 are disposed so that their rotational axes are substantially parallel to each other. The rotational axes of these screws are also substantially parallel to the rotational axis of the first developing roller 30.

The developer supplying screw 42 is positioned between the first developing roller 30 and the developer stirring screw 43, and between itself and the developer stirring screw 43, a partition wall 48 of the developing container 60 is provided. The partition wall 48 of the developing container 60 is extended along rotational axis directions of the developer supplying screw 42 and the developer stirring screw 43. The partition wall 48 is provided with a communication opening (not shown) for establishing communication between a first feeding path 61 along which the developer is fed by the developer supplying screw 42 and a second feeding path 62 along which the developer is fed by the developer stirring screw 43 is provided.

12

The developer stirred by the developer collecting screw 44 passes through a communication opening (not shown) formed in a partition wall 63 of the developing container 60 positioned between the developer collecting screw 44 and the developer supplying screw 42 and then is dropped toward the developer supplying screw 42 by its own weight. The above-described guiding member is formed integrally with the partition wall 63, and above the partition wall 63, the developer collecting screw 44 is disposed.

10 A position of the communication opening through which the developer stirred by the developer collecting screw 44 is dropped by its own weight and is guided into the developer circulating portion 46 may preferably be disposed while avoiding a region (an intermediary portion with respect to the rotational axis direction of the developer supplying screw 42) in which the developer is supplied toward the first developing roller 30. In this embodiment, the position of the communication opening is a position where the communication opening position is included in a range of a downstream end portion (terminal portion) with respect to a developer feeding direction of the first feeding path 61 in which the developer supplying screw 42 is disposed.

Developer feeding directions of the developer supplying screw 42 and the developer stirring screw 43 are mutually opposite directions. Further, a starting end side (upstream end side in the developer feeding direction) and a terminal end side (downstream end side in the developer feeding direction) of the first feeding path 61 in which the developer supplying screw 42 is disposed, and a terminal end side and 20 a starting end side of the second feeding path 62 in which the developer stirring screw 43 is disposed communicate with each other, respectively, via communication openings provided in the partition wall 48. Accordingly, the developer is circulated in the rotational directions of the developer supplying screw 42 and the developer stirring screw 43 indicated by arrows in FIG. 2 and in the substantially horizontal direction in the developing container 60, so that a part of the developer is supplied toward the first developing roller 30.

25 A developer supply opening 51 (see FIG. 2) is provided above the developer stirring screw 43 in the developing container 60 and is connected to the developer storage portion 27Y (see FIG. 1). Further, the developer supply opening 51 is constituted so as to be capable of supplying the developer, accommodated in a bottle mounted in the developer storage portion 27Y, to the second feeding path 62 in which the developer stirring screw 43 is disposed.

30 As described above, a toner weight ratio of the developer accommodated in the bottle of the developer storage portion 27Y is larger than a toner weight ratio of the developer in the developing device 1Y, and therefore, by adjusting an amount of the developer supplied to the developer stirring screw 43, the toner weight ratio of the developer in the developing device 1Y can be maintained at a certain level.

35 A toner concentration detecting sensor 49 (see FIG. 2) is provided for detecting a toner concentration of the developer contained in the developer circulating portion 46. The toner concentration detecting sensor 49 is a sensor for detecting (magnetic) permeability. The toner concentration corresponds to a consumption amount of the toner in the developing device 1Y, and therefore, is utilized in control of supply of the developer from the developer storage portion 27Y. For example, when the toner concentration is detected that the toner concentration is lowered than a predetermined value, the developer is supplied from the developer storage portion 27Y. Incidentally, the permeability changes depending on the toner concentration, and therefore, by utilizing the permeability, it is possible to detect the toner concentration.

The regulating member 50 is disposed adjacent to the first developing roller 30 and is used for regulating an amount of the developer supplied from the developer circulating portion 46 to the first developing roller 30. The regulating member 50 can be constituted so as to regulate an amount of the developer attracted to the first developing roller 30, on the basis of a gap between the surface of the first sleeve 33 of the first developing roller 30 and an end portion of the regulating member 50.

A circulating path of the developer in the developing container 60 is such that the developer is fed in the substantially horizontal direction while being stirred in the developer circulating portion 46 and thereafter is supplied to the first developing roller 30, and then is delivered from the first developing roller 30 to the second developing roller 31 positioned above the first developing roller 30, on the basis of the magnetic force. Then, the developer is delivered from the second developing roller 31 to the peeling roller 32 positioned beside the second developing roller 31, on the basis of the magnetic force again, and thereafter, is peeled off from the peeling roller 32 by the third magnet 38 included in the peeling roller 32. Further, the developer is collected by the developer collecting portion 47 and then is guided again into the developer circulating portion 46.

Further, as described above, in this embodiment, a two-component development type is used as a development type, and as the developer, a developer obtained by mixing non-magnetic toner having a negative charging property with a carrier having a magnetic property is used. The non-magnetic toner is toner obtained by containing a colorant, a wax component, and the like in a resin such as polyester or styrene-acrylic resin, by forming the mixture in powder through pulverization or polymerization, and then by adding fine powder of titanium oxide, silica, or the like to a surface of the powder. The magnetic carrier is a carrier obtained by coating a resin material on a surface layer of a core comprising ferrite particles or resin particles obtained by kneading with magnetic powder. The toner concentration in the developer (a weight ratio of the toner to the developer) in an initial state is 8% in this embodiment.

In general, the two-component development type using the toner and the carrier has a feature such that stress exerted on the toner is less than stress exerted on the toner in a one-component development type using a one-component developer because the toner and the carrier are charged to predetermined polarities by subjecting the toner and the carrier to triboelectric contact. On the other hand, by long-term use, an amount of a contaminant (spent) deposited on the carrier surface increases, and therefore, toner charging capacity gradually lowers. As a result, problems of a fog and a toner scattering arise. Although it would be considered that an amount of the carrier accommodated in the developing device is increased in order to prolong a lifetime of the two-component developing device, this causes upsizing of the developing device, and therefore is not desirable.

In order to solve the above-described problems on the two-component developer, in this embodiment, an ACR (auto carrier refresh) type is employed. The ACR type is a type such that an increase in amount of a deteriorated developer is suppressed by not only supplying a fresh developer little by little from the developer storage portion 27Y into the developing device 1Y but also discharging the developer, deteriorated in charging performance, little by little through a discharge opening (not shown) of the developing device 1Y. By this, the deteriorated carrier in the developing device 1Y is replaced little of little with a fresh

carrier, so that the charging performance of the carrier in the developing device 1Y can be maintained at an approximately constant level.

[Magnetic Poles of Magnets]

Next, magnetic pole constitutions of the first magnet 36, the second magnet 37, and the third magnet 38 included in the first developing roller 30, the second developing roller 31, and the peeling roller 32, respectively, which are shown in FIGS. 3, 4, and 5, respectively, will be described.

As shown in FIG. 3, the first magnet 36 included in the first developing roller 30 has a 7-pole-based magnetic pole constitution including a plurality of magnetic poles 101, 102, 103, 104, 105, 106, and 107. Of these magnetic poles, the magnetic pole 106 is a delivering pole for delivering the developer from the first developing roller 30 to the second developing roller 31. The magnetic poles 101 to 107 are disposed in a named order in the rotational direction of the first sleeve 33. The magnetic pole 101 is an S pole and is disposed in a position opposing the regulating member 50 through the first sleeve 33, and adjusts an amount of the developer conveyed on the first sleeve 33 as described above. The magnetic pole 104 as a first developing pole is an N pole and is disposed in a position opposing the photosensitive drum 28Y through the first sleeve 33, and is a magnetic pole for developing the electrostatic latent image, formed on the photosensitive drum 28Y, with the developer. Hereinafter, the magnetic pole 104 is referred to as the first developing pole 104 in some cases.

The magnetic pole 106 as a delivering pole is the N pole and is a magnetic pole for delivering the developer from the first sleeve 33 to the second sleeve 34 by a magnetic field generated in cooperation with the second magnet 37 of the second developing roller 31, and is hereinafter referred to as a delivering pole 106 in some cases.

The magnetic pole 107 is the N pole and is used for attracting the developer, supplied from the developer supplying screw 42, to the first sleeve 33. The magnetic poles 102, 103, and 105 are the N pole, the S pole, and the S pole, respectively, and are used as feeding poles for feeding upward the developer attracted by the magnetic pole 107 with rotation of the first sleeve 33. Of these magnetic poles, the magnetic pole 105 is a first magnetic pole upstream of and adjacent to the delivering pole 106 with respect to the rotational direction of the first sleeve 33, and is hereinafter referred to as a first feeding pole 105 in some cases. The first developing pole 104 is positioned upstream of and adjacent to the first feeding pole 105 with respect to the rotational direction of the first sleeve 33.

Further, the magnetic pole 107 is disposed on a side downstream of the delivering pole 106 with respect to the rotational direction of the first sleeve 33 and has the same polarity as the delivering pole 106. The delivering pole 106 and the magnetic pole 107 form a low-magnetic force portion 110 lower in magnetic force than the delivering pole 106 by a repelling magnetic field therebetween in cooperation with each other. By this low-magnetic force portion 110, the developer is peeled off from the first sleeve 33, and delivery of the developer from the first sleeve 33 to the second sleeve 34 is promoted. Incidentally, the low-magnetic force portion 110 may have substantially no magnetic force in this embodiment, but may have a low magnetic force, and for example, may be a magnetic pole of 5 mT or less in magnetic force (normal component Br of magnetic flux density). The same applies to a low-magnetic force portion 210 of the second magnet 37 shown in FIG. 4 and a low-magnetic force portion 310 of the third magnet 38 shown in FIG. 5.

15

As shown in FIG. 4, the second magnet 37 included in the second developing roller 31 has a seven-magnetic pole-based constitution including a plurality of magnetic poles 202, 203, 204, 205, 206 and 207. Of these, the magnetic pole 201 is a receiving pole for receiving the developer from the first developing roller 30 by the second developing roller 31. The magnetic poles 201 to 207 are disposed in a named order in the rotational direction of the second sleeve 34.

The magnetic pole 201 is a magnetic pole for attracting the developer from the first sleeve 33 to the second sleeve 34 by a magnetic field generated in cooperation with the magnetic pole 106 of the first magnet 36 of the first developing roller 30. The magnetic pole 207 is a magnetic pole for delivering the developer from the second sleeve 34 to the third sleeve 35 by a magnetic field generated in cooperation with the third magnetic 38 of the peeling roller 32.

Further, the magnetic pole 201 is the S pole different in polarity from the delivering pole 106 and is used for attracting the developer from the first developing roller 30 (first sleeve 33) to the second sleeve 34 as described above. The magnetic pole 203 as a second developing pole is the S pole and is a magnetic pole which is disposed in a position opposing the photosensitive drum 28Y through the second sleeve 34 and which is for developing the electrostatic latent image formed on the photosensitive drum 28Y. Hereinafter, the magnetic pole 203 is referred to as a second developing pole 203 in some cases.

The magnetic poles 202, 204, 205 and 206 are the N pole, the N pole, the S pole, and the N pole, and are used for feeding upward the developer attracted by the magnetic pole 201 with rotation of the second sleeve 34. Of these magnetic poles, the magnetic pole 202 is a second magnetic pole positioned downstream of and adjacent to the receiving pole 201 with respect to the rotational direction of the second sleeve 34, and is hereinafter referred to as a second feeding pole 202 in some cases. The second developing pole 203 is positioned downstream of and adjacent to the second feeding pole 202 with respect to the rotational direction of the second sleeve 34. The magnetic pole 207 is the S pole and delivers the developer, after passing through a developing region with the photosensitive drum 28Y corresponding to the magnetic pole 203, from the second sleeve 34 to the third sleeve 35 opposing the second sleeve 34 by a magnetic field generated in cooperation with a magnetic pole 303 in the third magnet 38 included in the peeling roller 32.

Further, the magnetic pole 207 is disposed on a side upstream of the receiving pole 201 with respect to the rotational direction of the second sleeve 34 and has the same polarity as the receiving pole 201. The receiving pole 201 and the magnetic pole 207 form the low-magnetic force portion 210 lower in magnetic force than the magnetic pole 207 by a repelling magnetic field generated in cooperation with each other. By this low-magnetic force portion 210, the developer is peeled off from on the second sleeve 34, and delivery of the developer from the first sleeve 33 to the second sleeve 34 is promoted. Further, by the low-magnetic force portion 210, it is possible to prevent attraction of the developer to a closest portion between the first sleeve 33 and the second sleeve 34, and pressure exerted on the developer can be suppressed.

As shown in FIG. 5, the third magnet 38 included in the peeling roller 32 is provided with a plurality of magnetic poles 301, 302, 303, 304, and 305. The magnetic poles 301 to 305 are disposed in a named order in the rotational direction of the third sleeve 35.

16

The magnetic pole 303 is the N pole different polarity from the magnetic pole 207 and is used for attracting the developer, peeled off from the second sleeve 34 as described above, to the third sleeve 35. The magnetic poles 301, 302, and 304 are the N pole, the S pole, and the S pole are used for feeding the developer on the third sleeve 35 with rotation of the third sleeve 35. Particularly, the magnetic pole 304 is used for feeding downward the developer attracted by the magnetic pole 303 with rotation of the third sleeve 35. The magnetic pole 305 is the N pole and is peeling pole used for peeling off the developer, attracted to the third sleeve 35, from the third sleeve 35 by a repelling magnetic field generated in cooperation with the magnetic pole 301 having the same polarity as the magnetic pole 305.

[Magnetic Pole Arrangement Relationship]]

Next, a magnetic pole arrangement relationship between the first magnet 36 and the second magnet 37 disposed inside the first developing roller and the second developing roller 31, respectively, will be described using FIGS. 6 to 9. FIG. 6 is a conceptual view for illustrating an arrangement of the first developing roller 30 and the second developing roller 31 in this embodiment, and particularly shows a layout of the first feeding pole 105 and the delivering pole 106 of the first magnet 36 of the first developing roller 30, and the receiving pole 201 and the second feeding pole 202 of the second magnet 37 of the second developing roller 31. Incidentally, due to complication, a part of the magnetic poles is omitted from display. Further, FIGS. 7 and 8 are graphs each showing a magnetic characteristic of the first magnet 36 of the first developing roller 30. FIG. 9 is a conceptual view for illustrating a magnetic field of the first developing roller 30 and the second developing roller 31 of this embodiment, and particularly, show absolute values of magnetic flux densities of the delivering pole 106, the first feeding pole 105, the receiving pole 201, and the second feeding pole 202, and states of magnetic flux lines (lines of magnetic flux) formed by these magnetic poles.

In this embodiment, as described above, the developer in the developing device 1Y is moved from the surface of the first sleeve 33 of the first developing roller 30 to the surface of the second sleeve 34 of the second developing roller 31 by magnetic fields of the delivering pole 106 in the first developing roller 30 and the receiving pole 201 in the second developing roller 31, and then is moved onto the surface of the third sleeve 35 of the peeling roller 32 after being used in a developing step of the electrostatic latent image on the photosensitive drum 28Y.

A process (arrow F1) in which the developer is delivered from on the first sleeve 33 of the first developing roller 30 onto the second sleeve 34 of the second developing roller 31 will be described. As indicated by the arrow F1 in FIGS. 6 and 9, the developer is moved to a downstream side of the rotational direction 81 of the first sleeve 33 rotating about the rotation center R1 by a magnetic force along magnetic flux lines extending from the first feeding pole 105 to the delivering pole 106 of the first magnet 36. Then, the developer is moved from on the first sleeve 33 onto the second sleeve 34 by a magnetic force along magnetic flux lines extending from the delivering pole 106 to the receiving pole 201. Further, the developer is moved toward a downstream side of the rotational direction 82 of the second sleeve 34 rotating about the rotation center R2 by a magnetic force along magnetic flux lines extending from the receiving pole 201 toward the second feeding pole 202.

Here, a position (peak position) of a maximum (value) (peak value) of a normal component of a magnetic flux density of the delivering pole 106 on the surface of the first

sleeve 33 is taken as a point T (FIG. 8). Further, of half-value positions of the maximum value of the normal component of the magnetic flux density of the delivering pole 106, a downstream-side position with respect to the rotational direction of the first sleeve 33 is taken as Hd, and an upstream-side position with respect to the rotational direction of the first sleeve 33 is taken as Hu. Further, rectilinear lines L1, L2, L3, L4, L10, L11, and L12 which are indicated by chain lines in FIGS. 6 and 8 are defined as follows:

- L1: horizontal line passing through rotation center R1 of first sleeve 33,
- L2: horizontal line passing through rotation center R2 of second sleeve 34,
- L3: vertical line passing through rotation center R1 of first sleeve 33,
- L4: rectilinear line passing through rotation center R1 and rotation center R2,
- L10: rectilinear line connecting rotation center R1 and point T (magnetic flux density peak position of delivering pole 106) (FIG. 8),
- L11: rectilinear line connecting rotation center R1 and point Hd (downstream-side position of half value of magnetic flux density peak value of delivering pole 106 with respect to rotational direction 81 of first sleeve 33) (FIG. 8), and
- L12: rectilinear line connecting rotation center R1 and point Hu (upstream-side position of half value of magnetic flux density peak value of delivering pole 106 with respect to rotational direction 81 of first sleeve 33) (FIG. 8).

Feeding of the developer from the first feeding pole 105 to the delivering pole 106 of the first sleeve 33 is made by a force by rotation of the first sleeve 33 and a magnetic force along magnetic flux lines extending from the first feeding pole to the delivering pole 106. The peak value of the magnetic flux density of the delivering pole 106 is not more than a peak value (maximum of normal component) of the magnetic flux density of the receiving pole 201. Further, a magnetic field (delivering magnetic field) which is formed by the delivering pole 106 and the receiving pole 201 and which is for delivering the developer from the first sleeve 33 to the second sleeve 34 is constituted so that a repulsive force region in which the magnetic force in the direction of the rotation center R1 in the neighborhood of an outer peripheral surface of the first sleeve 33 becomes negative in polarity is generated in a range on a side upstream of a point P1 of intersection between the rectilinear line L4 and the first sleeve 33 (FIG. 6) and downstream of the magnetic flux density peak position (maximum value position of normal component on the surface of the first sleeve 33) of the first feeding pole 105 with respect to the rotational direction 81 of the first sleeve 33.

The delivering magnetic field is constituted so that an attracting force region in which the magnetic force in the direction of the rotation center R2 in the neighborhood of an outer peripheral surface of the second sleeve 34 becomes positive in polarity is generated in a range on a side downstream of a point P2 of intersection between the rectilinear line L4 and the second sleeve 34 (FIG. 6) and upstream of the magnetic flux density peak position of the second feeding pole 202 with respect to the rotational direction 82 of the second sleeve 34. By such a magnetic force relationship, delivery of the developer from the first sleeve 33 to the second sleeve 34 is carried out.

Incidentally, the magnetic flux lines extending from the first feeding pole 105 are connected to not only the delivering pole 106 but also the second feeding pole 202, of the

second developing roller 31, constituted by the N pole different in polarity from the first feeding pole 105. When as regards a magnetic force acting on the developer on the first sleeve 33 in the neighborhood of the first feeding pole 105, a magnetic field between the first feeding pole 105 and the second feeding pole 202 becomes predominant over a magnetic field between the first feeding pole 105 and the delivering pole 106, as indicated by an arrow F2 in FIG. 6, movement of the developer from the first feeding pole 105 to the second feeding pole 202 or from the second feeding pole 202 to the first feeding pole 105 occurs. Further, the developer also contacts the photosensitive drum 28Y in the neighborhood of these magnetic poles, so that a fog image in a vertical stripe shape is generated on the photosensitive drum 28Y.

In order to suppress such a movement of the developer in the arrow F2 direction, it may only be required that the magnetic field between the first feeding pole 105 and the second feeding pole 202 is weakened and that the magnetic field between the first feeding pole 105 and the delivering pole 106 is strengthened. As a method therefor, a method in which the magnetic flux density peak value of the delivering pole 106 is increased would be considered. However, when the magnetic flux density peak value of the delivering pole 106 is increased, a force for constraining the developer in the neighborhood of a closest position between the first sleeve 33 and the second sleeve 34 becomes strong and thus pressure is exerted on the developer, so that deterioration of the developer is accelerated. When the developer is deteriorated, a charge amount of the toner lowers, so that there is a liability that the electrostatic latent image cannot be developed on the photosensitive drum 28Y with the toner in an appropriate amount.

Further, in a range on a side upstream of the point P1 of intersection between the rectilinear line L4 and the first sleeve 33 and downstream of the magnetic flux density peak position of the first feeding pole 105 with respect to the rotational direction 81 of the first sleeve 33, the repulsive force region in which the magnetic force in the direction of the rotation center R1 in the neighborhood of the outer peripheral surface of the first sleeve 33 becomes negative in polarity is narrowed or eliminated, so that delivery of the developer from the first sleeve 33 to the second sleeve 34 is not readily performed appropriately in some cases. When such an improper delivery of the developer occurs, there are possibilities that the developer is carried and moved on the first sleeve 33 and thus non-uniformity of the toner concentration of the developer on the first sleeve 33 occurs and that a stagnation amount of the developer in the neighborhood of the closest position between the first sleeve 33 and the second sleeve 34 is gradually increased and thus an overflowing phenomenon such that a supply amount of the developer to the second sleeve 34 becomes excessive occurs.

For the above-described reasons, it is not preferable that the magnetic flux density peak value of the delivering pole 106 is simply increased. Therefore, in this embodiment, the delivering pole 106 is set as follows. First, as shown in FIG. 8, of half-value widths of the magnetic flux density peak value of the delivering pole 106, an angle formed by the rectilinear lines L10 and L12, which is a width on a side upstream of the magnetic flux density peak position of the delivering pole 106 is taken as an angle w1, and an angle, formed by the rectilinear lines L10 and L11, which is a width on a side downstream of the magnetic flux density peak position of the delivering pole 106 is taken as w2. Further, an angle difference (w1-w2) of the angle w2 relative to the

angle w_1 is Δw , i.e., $\Delta w = w_1 - w_2$. In this case, the delivering pole **106** is set to satisfy: $\Delta w \geq 0$.

By this, the magnetic field between the first feeding pole **105** and the second feeding pole **202** is weakened, and the magnetic field between the first feeding pole **105** and the delivering pole **106** is strengthened. Further, a feeding property of the developer from the first feeding pole **105** to the delivering pole **106** of the first sleeve **33** is improved. As a result of this, it becomes possible to suppress movement of the developer between the first feeding pole **105** of the first developing roller **30** and the second feeding pole **202** of the second developing roller **31**.

A magnetic property distribution of the first magnet **36** in this embodiment is shown in each of FIGS. 7 to 9. A graph of FIG. 7 shows positions with respect to an angle direction of the first sleeve **33** and magnitudes of magnetic flux densities in a normal direction, of the magnetic poles **101** to **107** included in the first magnet **36** shown in FIGS. 3 and 6. In FIG. 7, an abscissa represents an angle (indicated by an arrow in FIG. 6) of the first magnet **36** with respect to the rotational direction of the first sleeve **33** when a position of the magnet **36** on the photosensitive drum **28Y** side relative to the horizontal line **L1** on the rotation center **R1** of the first developing roller **30** is taken as 0 degrees. In FIG. 7, an ordinate represents a measurement result of the magnetic flux density of the first magnet **36** with respect to the normal direction at an associated angle of the first magnet **36** with respect to the rotational direction.

FIG. 8 shows a portion in the neighborhood of the first feeding pole **105** and the delivering pole **106** in FIG. 7 in an enlarged manner, in which the rectilinear lines **L1** to **L4** and **L10** to **L12** on the above-described first sleeve **33** are indicated by chain lines, and magnitudes of the angles w_1 and w_2 are indicated by double-pointed arrows in FIG. 8. In the first magnet **36** in this embodiment, the delivering pole **106** is set to provide the angle $w_1 = 11$ degrees and the angle $w_2 = 6$ degrees so as to satisfy an angle difference $\Delta w = 5$ degrees. Here, set values employed in this embodiment are examples, and the above-described angle difference Δw may only be required to satisfy a relationship of $\Delta w \geq 0$ and may preferably satisfy a relationship of $\Delta w \geq 0$. By satisfying such a relationship, the developer on the first sleeve **33** is easily fed from the first feeding pole **105** to the delivering pole **106**.

FIG. 9 is a schematic view showing an arrow **F1** which shows motion of the developer from the first feeding pole **105** on the first sleeve **33** to the second feeding pole **202** on the second sleeve **34**, a state of magnetic flux lines formed by the first feeding pole **105**, the delivering pole **106**, the receiving pole **201**, and the second feeding pole **202**, and absolute values of magnetic flux density magnitudes of these magnetic poles in the normal direction. In this embodiment, the first feeding pole **105** and the receiving pole **201** are constituted by the S poles, and the delivering pole **106** and the second feeding pole **202** are constituted by the N poles. The magnetic poles to which the first feeding pole **105** which is the S pole is connected by magnetic flux lines are the delivering pole **106** and the second feeding pole **202** which are the N poles.

Here, as described above, a shape of the magnetic flux density of the delivering pole **106** is set so that of the half-value widths of the magnetic flux density peak value of the delivering pole **106** in the normal direction of the delivering pole **106**, the upstream-side angle w_1 is the downstream-side angle w_2 or more. Thus, of the half-value widths of the magnetic flux density of the delivering pole **106** close to the first feeding pole **105**, the upstream-side angle w_1 is widened, so that a magnetic field between the

first feeding pole **105** and the delivering pole **106** is strengthened, and a magnetic field between the first feeding pole **105** and the second feeding pole **202** is weakened. Further, occurrence of movement of the developer between the first feeding pole **105** and the second feeding pole **202** as indicated by the arrow **F2** is suppressed, so that occurrence of an abnormal image (image in vertical stripe shape) due to this can be suppressed.

Further, in order to weaken the magnetic field between the first feeding pole **105** and the second feeding pole **202**, in comparison with simply increasing the magnetic flux density peak value of the delivering pole **106** in the normal direction of the delivering pole **106**, by employing a constitution in which only the upstream-side angle of the half-value widths of the magnetic flux density of the delivering pole **106** close to the first feeding pole **105** is increased such that the angle difference of $\Delta w \geq 0$, it becomes possible to suppress an increase in force for constraining the developer in the neighborhood of the closest position between the first sleeve **33** and the second sleeve **34**. Further, with respect to the rotational direction **81** of the first sleeve **33**, in a range on the side upstream of the point **P1** of intersection between the rectilinear line **L4** and the first sleeve **33** and downstream of the magnetic flux density peak position of the first feeding pole **105**, the repelling force region in which the magnetic force in the direction of the rotation center **R1** in the neighborhood of the outer peripheral surface of the first sleeve **33** is negative in polarity is not eliminated, so that delivery of the developer from the first sleeve **33** to the second sleeve **34** is appropriately performed.

Incidentally, of the first magnet **36**, a part of the magnet forming the delivering pole **106** with respect to a circumferential direction is cut away, or a magnet different in magnetic force is embedded in the cut-away portion, so that as described above, a magnetic flux density distribution of the delivering pole **106** may be made asymmetric.

Next, a comparison example for comparison with this embodiment will be described using FIGS. 10 to 12. In the comparison example, a magnetic characteristic distribution of a delivering pole **106A** is set so that the angle difference Δw satisfies $\Delta w < 0$. FIGS. 10 to 12 show states of magnetic fields formed by the first feeding pole **105**, the delivering pole **106A**, the receiving pole **201**, and the second feeding pole **202** in such a comparison example.

A graph shown in FIG. 10 is a magnetic characteristic in the comparison example in which positions, with respect to an angle direction, of magnetic poles included in the first magnet **36** and magnitudes of the magnetic flux density disclosed in FIGS. 3 and 6 are shown, and is a graph similar to the graph of the above-described FIG. 7 except for the delivering pole **106A**. FIG. 11 is a graph in which a position in the neighborhood of the delivering pole **106A** and the first feeding pole **105** in FIG. 10 is enlarged, wherein the above-described rectilinear lines **L1** to **L4** and **L10** to **L12** on the first sleeve **33** are indicated by chain lines, and magnitudes of the angle w_1 and the angle w_2 are shown by double-pointed arrows. The delivering pole **106A** of the first magnet **36** in the comparison example has the same magnetic flux density peak value as that of the above-described delivering pole **106** and has a constitution of $\Delta w < 0$ in which the downstream side width of the half-value width is wide, and the angles w_1 and w_2 are set to $w_1 = 6$ degrees and $w_2 = 11$ degrees.

FIG. 12 is a schematic view showing the arrow **F1** showing motion of the developer from the first feeding pole **105** on the first sleeve **33** to the second feeding pole **202** on the second sleeve **34**, a state of magnetic flux lines formed

by the first feeding pole **105**, the delivering pole **106A**, the receiving pole **201**, and the second feeding pole **202**, and absolute values of the magnetic flux density magnitudes of these magnetic poles in the normal direction.

As described above, a shape of the magnetic flux density of the delivering pole **106A** in the comparison example is set so that the angle w_1 is smaller than the angle w_2 . Thus, in a constitution in which the upstream-side angle w_1 of the half-value widths of the delivering pole **106A** close to the first feeding pole **105** is narrow, the magnetic field between the first feeding pole **105** and the delivering pole **106A** is weak, and the magnetic field between the first feeding pole **105** and the second feeding pole **202** cannot be sufficiently weakened. For this reason, movement of the developer between the first feeding pole **105** and the second feeding pole **202** occurs, so that the above-described fog image in the vertical stripe shape occurs. That is, non-uniformity occurs in coating state of the developer on the second sleeve **34**, and an uneven image occurs on an output image. On the other hand, in this embodiment, the magnetic characteristic of the first magnet **36** is characteristics as shown in FIGS. 8 and 9, and therefore, occurrences of the unevenness in the output image and the image in the vertical stripe shape as in the comparison example can be suppressed.

[Experiment]

Next, an experiment in which an occurrence status of a stripe-shaped fog image (abnormal image) in the above-described constitution was checked will be described. In the example, the angle w_1 and the angle w_2 in the magnetic flux density distribution of the delivering pole **106** were changed, and images were outputted by image forming apparatuses in which delivering poles in various conditions are incorporated. Then, the occurrence status of the stripe-shaped fog image on the output image was checked.

In the experiment, the occurrence status of the stripe-shaped fog image on the output image was evaluated in the following manner.

Solid white images were formed on 10 A3-sized sheets, and the number of vertical stripes on the output image was measured.

In the case where there was no vertical stripe on the solid white images on the 10 A3-sized sheets, the solid white images were formed on 100 A3-sized sheets and then the vertical stripes were checked.

A result of this experiment was shown in tables 1 and 2.

TABLE 1

w1(°), w2(°)	(6, 11)	(6, 8.5)	(6, 7.5)	(6, 6)	(8.5, 6)	(11, 6)	(13.5, 6)	(16, 6)
Δw(w1 - w2) (°)	-5	-2.5	-1.5	0	2.5	5	7.5	10
AI*1	X	X	X	○	○	○	○	○

*1:AI" is the abnormal image.

TABLE 2

w1(°), w2(°)	(4, 10)	(4, 7)	(4, 5.5)	(4, 4)	(6.5, 4)	(7.5, 4)	(9, 4)	(12, 4)
Δw(w1 - w2) (°)	-6	-3	-1.5	0	2.5	3.5	5	8
AI*1	X	X	X	Δ	○	○	○	○

*1:AI" is the abnormal image.

Symbols in a row of the abnormal image in each of the tables 1 and 2 are results of evaluation of the occurrence status of the stripe-shaped fog image (abnormal image), and contents thereof are as follows.

x: On a single A3-sized sheet, 10 or more vertical stripes were recognized.

Δ: On the single A3-sized sheet, about one vertical stripe was recognized.

○: On 10 A3-sized sheets, about one vertical stripe was recognized.

In the develop evaluation, "o" shows a level such that the abnormal image does not substantially occur practically.

The constitutions of the first developing roller **30** and the second developing roller **31** are as shown in FIG. 6. The magnetic characteristic was such that the magnetic flux density peak value of the delivering pole **106** was fixed to about 36 mT and that a shape of the magnetic flux density in the neighborhood of the delivering pole **106** relative to the rotation angle of the first sleeve **33** was changed. As a method of changing the magnetic flux density, it is possible to change the magnetic flux density by changing a condition when the delivering pole **106** carried on the first magnet **36** is magnetized or by cutting away a part of the magnet, or the like. Incidentally, the magnetic poles other than the delivering pole **106** are as shown in FIGS. 7 to 10.

The table 1 shows the result in the case where with a state, as a center, in which the upstream-side angle w_1 and the downstream-side angle w_2 are equal to each other at 6 degrees (°), only the angle w_1 is increased or only the angle w_2 is increased. In the case where the angle difference $Δw$ which is a difference of the angle w_2 from the angle w_1 is $Δw < 0$, i.e., in the case where the angle w_1 is smaller than the angle w_2 , it was found that the occurrence of the abnormal image cannot be suppressed. This is because as in the comparison example shown in FIG. 12, the angle w_1 adjacent to the first feeding pole **105** is small, and therefore, the magnetic field between the first feeding pole **105** and the second feeding pole **202** cannot be sufficiently weakened by the magnetic field between the first feeding pole **105** and the delivering pole **106**, and thus the developer is moved between the first feeding pole **105** and the second feeding pole **202**. Further, this can also be said as a result that the magnetic field between the first feeding pole **105** and the delivering pole **106** cannot be strengthened even when the angle w_2 which is not adjacent to the first feeding pole **105** is made large, and thus the magnetic field between the first feeding pole **105** and the second feeding pole **202** cannot be sufficiently weakened.

On the other hand, in the case of $Δw \geq 0$, i.e., in the case where the angle w_1 is not less than the angle w_2 , it was found that the occurrence of the abnormal image can be suppressed. This is because as described with reference to

FIG. 9, the angle w_1 adjacent to the first feeding pole **105** is large, and therefore, the magnetic field between the first feeding pole **105** and the delivering pole **106** becomes strong, and thus the magnetic field between the first feeding pole **105** and the second feeding pole **202** can be weakened. As a result of this, movement of the developer in the arrow F_2 direction between the first feeding pole **105** and the second feeding pole **202** can be suppressed, so that the occurrence of the abnormal image can be suppressed.

The table 2 shows the result in the case where with a state, as a center, in which the upstream-side angle w_1 and the downstream-side angle w_2 are equal to each other at $4(^{\circ})$, only the angle w_1 is increased or only the angle w_2 is increased. Similarly as the result of the table 1, it was found that the occurrence of the abnormal image can be suppressed by satisfying $\Delta w \geq 0$. However, in the condition of the table 2, in the angle difference $\Delta w = 0$, compared with the result of the table 1, the occurrence of the abnormal image cannot be sufficiently suppressed. This is because the half-value width of the delivering pole **106** when the angle difference Δw in the table 1 is $\Delta w = 0$ is 12 degrees, whereas the half-value width of the delivering pole **106** when the angle difference Δw in the table 2 is $\Delta w = 0$ is 8 degrees narrower than 12 degrees. When the half-value width is narrow, due to assembling tolerances of the first magnet **36** and the second magnet **37**, some change in magnetic pole position by the influence of variation in magnetization, and the like, the magnetic field between the delivering pole **106** and the first feeding pole **105** is changed in a weakening direction in some instances. In this case, an effect of weakening the magnetic field between the first feeding pole **105** and the second feeding pole **202** and suppressing movement of developer between the first feeding pole **105** and the second feeding pole **202** becomes small (weak). Accordingly, in the case where the half-value width is narrow, it is preferable that the angle difference $\Delta w > 0$ is satisfied. Further, it is further preferable that $\Delta w \geq 2.5$ degrees is satisfied.

As described above, according to this embodiment, occurrence of an image defect can be suppressed. That is, in the developing device **1Y** of this embodiment, the developer fed from the first feeding pole **105** to the delivering pole **106** on the first sleeve **33** and is delivered to the second sleeve **34** on the basis of the magnetic field between the delivering pole **106** and the receiving pole **201**, and then is fed on the second sleeve **34** from the receiving pole **201** to the second feeding pole **202**. In such a constitution, the developer is moved by the magnetic force along the magnetic field from the first feeding pole **105** to the second feeding pole **202** in some cases. On the other hand, in this embodiment, the delivering pole **106** satisfied $\Delta w \geq 0$ as described above, and therefore, the magnetic field between the first feeding pole **105** and the delivering pole **106** weakens the magnetic field between the first feeding pole **105** and the second feeding pole **202**, so that movement of the developer between the first feeding pole **105** and the second feeding pole **202** can be suppressed. For this reason, the occurrence of the above-described stripe-shaped fog image can be suppressed.

Particularly, even in an image forming apparatus in which an image forming speed (process speed) is high, the movement of the developer between the first feeding pole **105** and the second feeding pole **202** can be suppressed, so that the occurrence of the above-described stripe-shaped fog image can be suppressed. Further, the developer is stably circulated from the first developing roller **30** and then by the second developing roller **31**, the peeling roller **32**, and the developer circulating portion **46**, so that it is possible to provide the

developing device **1Y** and the image forming apparatus in which stable image output is carried out.

Second Embodiment

A second embodiment will be described using FIGS. 13 to 16. This embodiment is different from the first embodiment in constitution of a delivering pole **106B** of a first magnet **36** of a first developing roller **30**. Other constitutions and actions are similar to those in the first embodiment, and therefore, as regards similar constitutions, description and illustration are omitted or briefly made by adding the same reference numerals or symbols, and in the following, a difference from the first embodiment will be principally described.

In the case of the above-described first embodiment, as shown in FIG. 8, the magnetic flux density of the delivering pole **106** of the first magnet **36** included in the first developing roller **30** satisfies $\Delta w \geq 0$. The angle w_1 close to the first feeding pole **105** is large, and therefore, by the magnetic field between the first feeding pole **105** and the delivering pole **106**, the magnetic field between the first feeding pole **105** and the second feeding pole **202** can be weakened.

On the other hand, in this embodiment, as shown in FIGS. 13 and 14, in the position of the delivering pole **106** of the first magnet **36** employed in the first embodiment, a delivering pole **106B** is provided. A magnetic flux density peak value of this delivering pole **106B** is the same as the magnetic flux density peak value of the delivering pole **106**. On the other hand, a shape of the magnetic flux density peak value is changed to a flat shape.

This flat shape will be described. FIG. 15 shows a result of measurement of the magnetic flux density of the delivering pole **106B** in the normal direction of the delivering pole **106B**, in which the rotational direction of the first sleeve **33** is taken as the abscissa. That is, FIG. 15 is a graph showing a normal component of the magnetic flux density of the delivering pole **106B** on the surface of the first sleeve **33**, in which the ordinate represents the magnetic flux density, and the abscissa represents an angle of the first sleeve **33** with respect to the rotational direction of the first sleeve **33**. Here, in the following manner, values L_t and L_h , and rectilinear lines HL_t , HL_h , VL_{11} , and VL_{12} are defined:

L_t : peak value (maximum value of normal component) of magnetic flux density of delivering pole **106B** on surface of the first sleeve **33**,

L_h : half value of peak value L_t of magnetic flux density of delivering pole **106B**,

HL_t : rectilinear line parallel to abscissa passing through position of value L_t (broken line),

HL_h : rectilinear line parallel to abscissa passing through position of value L_h (broken line),

VL_{11} : rectilinear line parallel to ordinate passing through point Hd (chain line), and

VL_{12} : rectilinear line parallel to ordinate passing through point Hu (chain line).

Incidentally, Hd is similarly as the first embodiment, of half-value positions of the maximum value of the normal component of the magnetic flux density of the delivering pole **106B**, a downstream-side position with respect to the rotational direction of the first sleeve **33**. Further, Hu is, similarly as the first embodiment, of the half-value positions of the maximum value of the normal component of the magnetic flux density of the delivering pole **106B**, an upstream-side position with respect to the rotational direction of the first sleeve **33**.

Further, a rectangular area enclosed by the rectilinear lines VL11, VL12, HL_t, and HL_h is an area S, and in the graph of FIG. 15, an area (hatched portion) obtained by integrating the normal component of the magnetic flux density of the delivering pole 106B from the rectilinear line VL11 to the rectilinear line VL12 in terms of an angle with respect to the rotational direction of the first sleeve 33 is an area Sa.

As described above, in order to suppress the movement of the developer by weakening the magnetic field from the first feeding pole 105 to the second feeding pole 202, it is effective that the magnetic field between the first feeding pole 105 and the delivering pole 106B is strengthened. For this reason, it would be considered that the magnetic flux density peak value of the delivering pole 106B is made large, and by this, the magnetic field between the delivering pole 106B and the first feeding pole 105 can be strengthened. However, a magnetic field contributing to the delivery of the developer from the first sleeve 33 to the second sleeve 34 is also largely changed, and therefore, there is a possibility that the strengthened magnetic field leads to developer movement with rotation of the first sleeve 33 and deterioration of the developer.

Therefore, in this embodiment, the magnetic flux density peak value of the delivering pole 106B is not made large, but the area Sa which is an integrated value of values not less than the half value of the magnetic flux density peak value of the delivering pole 106B is made large. Specifically, a portion of the delivering pole 106B in the neighborhood of the magnetic flux density peak value position is formed in the flat shape so that the area ratio Sa/S of the area Sa to the area S becomes 75% or more (Sa/S $\geq$ 75%). As a result, the magnetic field between the first feeding pole 105 and the delivering pole 106B is strengthened, and thus the magnetic field between the first feeding pole 105 and the second feeding pole 202 can be weakened, so that the movement of the developer between the first feeding pole 105 and the second feeding pole 202 can be suppressed.

Incidentally, the constitution in which the shape of the delivering pole 106B in the neighborhood of the magnetic flux density peak value is flat is not limited to one peak, but may also be a plurality of peaks, and may only be required to be constituted so as to satisfy the area ratio Sa/S $\geq$ 75%. Further, a flat-shaped magnetic flux density distribution as in the delivering pole 106B may be formed by cutting away a part a magnet with respect to a circumferential direction, of the first magnet 36, forming the delivering pole 106B or by embedding a magnet different in magnetic force in the cut-away portion.

Further, the delivering pole 106B in this embodiment employs the flat shape of the magnetic flux density in the normal direction, extending toward an upstream side and a downstream side of the position of the magnetic flux density peak value in the normal direction of the delivering pole 106 in the first embodiment. For this reason, the magnetic field between the delivering pole 106B and the receiving pole 201 is formed widely, so that the influences on a change in magnetic field of the delivering pole 106B and the receiving pole 201 due to variation in magnetization and assembling tolerance of the first magnet 36 and the second magnet 37 becomes small. That is, in this embodiment, compared with the first embodiment, movement of the developer between the first feeding pole 105 and the second feeding pole 202 can be suppressed while widening a delivery latitude of the developer from the first sleeve 33 to the second sleeve 34 relative to a variation in magnetic pole arrangement of the first magnet 36 and the second magnet 37.

[Experiment]

Next, an experiment in which an occurrence status of a stripe-shaped fog image (abnormal image) in the above-described constitution was checked will be described. In the 5 experiment, by adjusting the magnetic flux density of the delivering pole 106B, the area S and the area Sa were changed, and images were outputted by image forming apparatuses in which delivering poles in various conditions are incorporated. Then, the occurrence status of the stripe-shaped fog image on the output image was checked.

Other conditions and evaluation of the experiment are the same as those of the experiment described in the first embodiment. A result of this experiment is shown in a table 3.

TABLE 3

	Sa[rad · mt], S[rad · mt]					
	(29, 48)	(36, 56)	(41, 61)	(46, 66)	(53, 71)	(59, 76)
Sa/S	60%	65%	67%	70%	75%	78%
AI*1	X	X	X	X	○	○

*1 "AI" is the abnormal image.

Constitutions of the first developing roller 30 and the second developing roller 31 in the experiment are as shown in FIG. 6. A magnetic characteristic is, as shown in FIG. 16, such that a magnetic flux density peak value of the delivering pole 106B was fixed to about 36 mT and that a shape 30 of the magnetic flux density in the neighborhood of the delivering pole 106B was changed stepwise from 60% to 78% in terms of the area ratio Sa/S.

Incidentally, in FIG. 16, the magnetic characteristic in the case where Sa/S is 60%, 70%, and 78% as a representative. The magnetic poles other than the delivering pole 106B are as shown in FIG. 13.

As is apparent from the table 3, when the area ratio Sa/S is 75% or more, occurrence of the abnormal image was able to be suppressed. This is an effect such that the neighborhood of the magnetic flux density peak value of the delivering pole 106B approaches the first feeding pole 105, and thus the magnetic field between the first feeding pole 105 and the delivering pole 106B is strengthened and the magnetic field between the first feeding pole 105 and the second feeding pole 202 is weakened. On the other hand, when the area ratio Sa/S is less than 75%, an effect of weakening the magnetic field between the first feeding pole 105 and the second feeding pole 202 by the magnetic fluxes of the delivering pole 106B was low, so that the developer was moved between the first feeding pole 105 and the second feeding pole 202, with the result that it was incapable of sufficiently suppressing the abnormal image.

As described above, according to this embodiment, occurrence of an image defect can be suppressed. That is, in the 55 developing device 1Y of this embodiment, the developer fed from the first feeding pole 105 to the delivering pole 106B on the first sleeve 33 and is delivered to the second sleeve 34 on the basis of the magnetic field from the delivering pole 106B to the receiving pole 201, and then is fed from the 60 receiving pole 201 to the second feeding pole 202. In such a constitution, the developer is moved by the magnetic force along the magnetic field from the first feeding pole 105 to the second feeding pole 202 in some cases. On the other hand, in this embodiment, the neighborhood of the magnetic 65 flux density peak value is constituted to have a flat shape so that the delivering pole 106B satisfies the area ratio Sa/S $\geq$ 75% as described above, so that the magnetic field

between the first feeding pole **105** and the delivering pole **106B** weakens the magnetic field between the first feeding pole **105** and the second feeding pole **202**, and therefore movement of the developer between the first feeding pole **105** and the second feeding pole **202** can be suppressed. For this reason, the occurrence of the above-described stripe-shaped fog image can be suppressed.

Third Embodiment

A third embodiment will be described using FIGS. 17 and 18. This embodiment is different from the first embodiment in constitution of a delivering pole **106C** of a first magnet **36** of a first developing roller **30**. Other constitutions and actions are similar to those in the first embodiment, and therefore, as regards similar constitutions, description and illustration are omitted or briefly made by adding the same reference numerals or symbols, and in the following, a difference from the first embodiment will be principally described.

In the case of the above-described second embodiment, as shown in FIG. 15, the integrated value S_a of values not less than the half value of the magnetic flux density peak value of the delivering pole **106B** of the first magnet **36** included in the first developing roller **30** is increased so that the area ratio S_a/S becomes 75% or more, and thus the magnetic field between the first feeding pole **105** and the delivering pole **106B** was strengthened, so that the magnetic field between the first feeding pole **105** and the second feeding pole **202** was weakened.

On the other hand, in this embodiment, as shown in FIG. 17, in the position of the delivering pole **106** of the first magnet **36** employed in the first embodiment, a delivering pole **106C** is provided. A magnetic flux density peak value of this delivering pole **106C** is the same as the magnetic flux density peak value of the delivering pole **106**. On the other hand, a shape of the magnetic flux density peak value is a shape close to a flat shape.

This flat shape will be described. FIG. 18 shows a result of measurement of the magnetic flux density of the delivering pole **106C** in the normal direction of the delivering pole **106C**, in which the rotational direction of the first sleeve **33** is taken as the abscissa. Here, as described in the following, values **C** and **D**, points **Cd**, **Cu**, **Dd**, and **Du**, rectilinear lines **L11C**, **L12C**, **L11D**, and **L12D**, and angles **Wc** and **Wd** are defined. Incidentally, a value **Lt** is a magnetic flux density peak value of the delivering pole **106C** similarly as in the second embodiment.

C: value of 10% of value **Lt**,

D: value of 90% of value **Lt**,

Cd: downstream-side position, with respect to rotational direction of first sleeve **33**, of positions where normal component of magnetic flux density of delivering pole **106C** becomes value **C**,

Cu: upstream-side position, with respect to rotational direction of first sleeve **33**, of positions where normal component of magnetic flux density of delivering pole **106C** becomes value **C**,

Dd: downstream-side position, with respect to rotational direction of first sleeve **33**, of positions where normal component of magnetic flux density of delivering pole **106C** becomes value **D**,

Du: upstream-side position, with respect to rotational direction of first sleeve **33**, of positions where normal component of magnetic flux density of delivering pole **106C** becomes value **D**,

L11C: rectilinear line connecting rotation center **R1** and first sleeve **33** and point **Cd** (chain line),

L12C: rectilinear line connecting rotation center **R1** and point **Cu** (chain line),

L11D: rectilinear line connecting rotation center **R1** and point **Dd** (chain line),

L12D: rectilinear line connecting rotation center **R1** and point **Du** (chain line),

Wc: angle formed by rectilinear line **L11C** and rectilinear line **L12C**, and

Wd: angle formed by rectilinear line **L11D** and rectilinear line **L12D**.

As described above, in order to suppress the movement of the developer between the first feeding pole **105** and the second feeding pole **202** by weakening the magnetic field from the first feeding pole **105** to the second feeding pole **202**, it is effective that the magnetic field between the first feeding pole **105** and the delivering pole **106C** is strengthened. For this reason, it would be considered that the magnetic flux density peak value of the delivering pole **106C** is made large, and by this, the magnetic field between the delivering pole **106C** and the first feeding pole **105** can be strengthened. However, a magnetic field contributing to the delivery of the developer from the first sleeve **33** to the second sleeve **34** is also largely changed, and therefore, there is a possibility that the strengthened magnetic field leads to developer movement with rotation of the first sleeve **33** and deterioration of the developer.

Therefore, in this embodiment, the magnetic flux density peak value of the delivering pole **106C** is not made large, but the angle **Wd** which is a 90%-value width of the magnetic flux density peak value of the delivering pole **106C** is made large. Specifically, a portion of the delivering pole **106C** in the neighborhood of the magnetic flux density peak value position is formed in the flat shape so that the angle ratio **Wd/Wc** of the angle **Wd** to the angle **Wc** which is a 10%-value width of the magnetic flux density peak value of the delivering pole **106C** becomes 45% or more ($Wd/Wc \geq 45\%$). As a result, the magnetic field between the first feeding pole **105** and the delivering pole **106C** is strengthened, and thus the magnetic field between the first feeding pole **105** and the second feeding pole **202** can be weakened, so that the movement of the developer between the first feeding pole **105** and the second feeding pole **202** can be suppressed.

Incidentally, the constitution in which the shape of the delivering pole **106C** in the neighborhood of the magnetic flux density peak value is flat is not limited to one peak, but may also be a plurality of peaks, and may only be required to be constituted so as to satisfy the angle ratio $Wd/Wc \geq 75\%$. Further, a flat-shaped magnetic flux density distribution as in the delivering pole **106C** may be formed by cutting away a part a magnet with respect to a circumferential direction, of the first magnet **36**, forming the delivering pole **106C** or by embedding a magnet different in magnetic force in the cut-away portion.

Further, the delivering pole **106C** in this embodiment employs the flat shape of the magnetic flux density in the normal direction, extending toward an upstream side and a downstream side of the position of the magnetic flux density peak value in the normal direction of the delivering pole **106** in the first embodiment. For this reason, the magnetic field between the delivering pole **106C** and the receiving pole **201** is formed widely, so that the influences on a change in magnetic field of the delivering pole **106C** and the receiving pole **201** due to variation in magnetization and assembling tolerance of the first magnet **36** and the second magnet **37**

becomes small. That is, in this embodiment, compared with the first embodiment, movement of the developer between the first feeding pole 105 and the second feeding pole 202 can be suppressed while widening a delivery latitude of the developer from the first sleeve 33 to the second sleeve 34 relative to a variation in magnetic pole arrangement of the first magnet 36 and the second magnet 37.

[Experiment]

Next, an experiment in which an occurrence status of a stripe-shaped fog image (abnormal image) in the above-described constitution was checked will be described. In the experiment, by adjusting the magnetic flux density of the delivering pole 106C, the angle W_c and the angle W_d were changed, and images were outputted by image forming apparatuses in which delivering poles in various conditions are incorporated. Then, the occurrence status of the stripe-shaped fog image on the output image was checked.

Other conditions and evaluation of the experiment are the same as those of the experiment described in the first embodiment. A result of this experiment is shown in a table 4.

TABLE 4

$W_d(^{\circ}), W_c(^{\circ})$	(5.6, 26)	(7.6, 27)	(9.6, 29)	(11.6, 29.3)	(13.7, 30.2)	(15.6, 30.8)
W_d/W_c	22%	28%	33%	40%	45%	51%
AI*1	X	X	X	X	○	○

*1:AI" is the abnormal image.

Constitutions of the first developing roller 30 and the second developing roller 31 in the experiment are as shown in FIG. 6. A magnetic characteristic is such that a magnetic flux density peak value of the delivering pole 106C was fixed to about 36 mT and that a shape of the magnetic flux density of the delivering pole 106C was changed stepwise from 22% to 51% in terms of the angle ratio W_d/W_c . The magnetic poles other than the delivering pole 106C are as shown in FIG. 13.

As is apparent from the table 4, when the angle ratio W_d/W_c is 45% or more, occurrence of the abnormal image was able to be suppressed. This is an effect such that the neighborhood of the magnetic flux density peak value of the delivering pole 106C approaches the first feeding pole 105, and thus the magnetic field between the first feeding pole 105 and the delivering pole 106C is strengthened and the magnetic field between the first feeding pole 105 and the second feeding pole 202 is weakened. On the other hand, when the angle ratio W_d/W_c is less than 45%, an effect of weakening the magnetic field between the first feeding pole 105 and the second feeding pole 202 by the magnetic fluxes of the delivering pole 106C was low, so that the developer was moved between the first feeding pole 105 and the second feeding pole 202, with the result that it was incapable of sufficiently suppressing the abnormal image.

As described above, according to this embodiment, occurrence of an image defect can be suppressed. That is, in the developing device 1Y of this embodiment, the developer fed from the first feeding pole 105 to the delivering pole 106C on the first sleeve 33 and is delivered to the second sleeve 34 on the basis of the magnetic field between the delivering pole 106C and the receiving pole 201, and then is fed on the second sleeve 34 from the receiving pole 201 to the second feeding pole 202. In such a constitution, the developer is moved by the magnetic force along the magnetic field between the first feeding pole 105 and the second feeding pole 202 in some cases. On the other hand, in this embodiment,

the neighborhood of the magnetic flux density peak value is constituted to have a flat shape so that the delivering pole 106C satisfies the angle ratio $W_d/W_c \geq 45\%$ as described above, so that the magnetic field between the first feeding pole 105 and the delivering pole 106C weakens the magnetic field between the first feeding pole 105 and the second feeding pole 202, and therefore movement of the developer between the first feeding pole 105 and the second feeding pole 202 can be suppressed. For this reason, the occurrence of the above-described stripe-shaped fog image can be suppressed.

Fourth Embodiment

15 A fourth embodiment will be described using FIG. 19. This embodiment is different from the first embodiment in constitution of a delivering pole 106D of a first magnet 36 of a first developing roller 30. Other constitutions and actions are similar to those in the first embodiment, and therefore, as regards similar constitutions, description and illustration are omitted or briefly made by adding the same

30 reference numerals or symbols, and in the following, a difference from the first embodiment will be principally described.

In this embodiment, as shown in FIG. 19, in the position 35 of the delivering pole 106 of the first magnet 36 employed in the first embodiment, a delivering pole 106D is provided. A magnetic flux density peak value of this delivering pole 106D is the same as the magnetic flux density peak value of the delivering pole 106. On the other hand, this embodiment is characterized that a shape of the magnetic flux density peak value of the delivering pole 106D is a shape close to a flat shape, and that of half values, an upstream-side width is wider than a downstream-side width. Specifically, a constitution satisfying the angle difference $\Delta w \geq 0$ described in the first embodiment and the area ratio $S_a/S \geq 70\%$ described in the second embodiment. Incidentally, in the case of this embodiment, different from the second embodiment, $\Delta w \geq 0$ is satisfied, and therefore, as regards the area ratio S_a/S , $S_a/S \geq 65\%$ may only be required to be satisfied. However, it is preferable that $S_a/S \geq 70\%$ is satisfied.

In such a case of this embodiment, the magnetic flux density of the delivering pole 106D on a side upstream of the magnetic flux density peak value of the delivering pole 106D in a range close to the first feeding pole 105 is larger 55 than the magnet flux densities of the delivering poles in the same range in the first embodiment and the second embodiment. For that reason, compared with the first and second embodiments, the magnetic field between the first feeding pole 105 and the delivering pole 106D is stronger and an effect of weakening the magnetic field between the first feeding pole 105 and the second feeding pole 202 is higher. For this reason, an effect of suppressing the movement of the developer between the first feeding pole 105 and the second feeding pole 202 becomes high.

60 [Experiment]

Next, an experiment in which an occurrence status of a stripe-shaped fog image (abnormal image) in the above-

described constitution was checked will be described. In the experiment, by adjusting the magnetic flux density of the delivering pole **106D**, the angle difference Δw and the area ratio Sa/S were changed, and images were outputted by image forming apparatuses in which delivering poles in various conditions are incorporated. Then, the occurrence status of the stripe-shaped fog image on the output image was checked.

Other conditions and evaluation of the experiment are the same as those of the experiment described in the first embodiment. A result of this experiment is shown in a table 5.

TABLE 5

Δw	-3	-1	0	2	3
Sa/S	61%	65%	70%	72%	74%
AI* ¹	X	Δ	○	○	○

*¹ "AI" is the abnormal image.

Constitutions of the first developing roller **30** and the second developing roller **31** in the experiment are as shown in FIG. 6. A magnetic characteristic is such that a magnetic flux density peak value of the delivering pole **106D** was fixed to about 36 mT and that the angle difference Δw was changed from $-3(^{\circ})$ to $3(^{\circ})$, and at the same time, a shape of the magnetic flux density of the delivering pole **106D** was changed stepwise from 61% to 74% in terms of the area ratio Sa/S . The magnetic poles other than the delivering pole **106D** are as shown in FIG. 7.

As is apparent from the table 5, when the angle difference Δw is $0(^{\circ})$ or more, and the area ratio Sa/S is 70% or more, occurrence of the abnormal image was able to be suppressed. This is an effect such that the neighborhood of the magnetic flux density peak value of the delivering pole **106D** approaches the first feeding pole **105**, and thus the magnetic field between the first feeding pole **105** and the delivering pole **106D** is strengthened and the magnetic field between the first feeding pole **105** and the second feeding pole **202** is weakened.

Further, even in the case of the angle difference $\Delta w=-1(^{\circ})$ and the area ratio $Sa/S=65\%$, the effect of suppressing the occurrence of the abnormal image was confirmed. However, in this condition, the magnetic field between the delivering pole **106D** and the first feeding pole **105** is changed in a weakening direction due to some change in magnetic pole position by the influence of assembling tolerances of the first magnet **36** and the second magnet **37**, and a variation in magnetization, so that an effect of weakening the magnetic field between the first feeding pole **105** and the second feeding pole **202** becomes low in some cases. For this reason, $\Delta w \geq 0$ may preferably be satisfied, and in this case, $Sa/S \geq 65\%$ may only be required to be satisfied. However, it is more preferable that the angle difference $\Delta w \geq 0$ and the area ratio $Sa/S \geq 70\%$ are satisfied.

As described above, according to this embodiment, occurrence of an image defect can be suppressed. That is, in the developing device **1Y** of this embodiment, the developer fed from the first feeding pole **105** to the delivering pole **106D** on the first sleeve **33** and is delivered to the second sleeve **34** on the basis of the magnetic field between the delivering pole **106D** and the receiving pole **201**, and then is fed on the second sleeve **34** from the receiving pole **201** to the second feeding pole **202**. In such a constitution, the developer is moved by the magnetic force along the magnetic field between the first feeding pole **105** and the second feeding pole **202** in some cases. On the other hand, in this embodiment,

the magnetic flux density of the delivering pole **106D** satisfies the angle difference $\Delta w \geq 0$ and the area ratio $Sa/S \geq 65\%$, preferably the area ratio $Sa/S \geq 70\%$ as described above, so that the magnetic field between the first feeding pole **105** and the delivering pole **106D** weakens the magnetic field between the first feeding pole **105** and the second feeding pole **202**, and therefore movement of the developer between the first feeding pole **105** and the second feeding pole **202** can be suppressed. For this reason, the occurrence of the above-described stripe-shaped fog image can be suppressed.

Fifth Embodiment

15 A fifth embodiment will be described using FIG. 20. This embodiment is different from the first embodiment in constitution of a delivering pole **106E** of a first magnet **36** of a first developing roller **30**. Other constitutions and actions are similar to those in the first embodiment, and therefore, as regards similar constitutions, description and illustration are omitted or briefly made by adding the same reference numerals or symbols, and in the following, a difference from the first embodiment will be principally described.

20 In this embodiment, as shown in FIG. 20, in the position of the delivering pole **106** of the first magnet **36** employed in the first embodiment, a delivering pole **106E** is provided. A magnetic flux density peak value of this delivering pole **106E** is the same as the magnetic flux density peak value of the delivering pole **106**. On the other hand, this embodiment is characterized that a shape of the magnetic flux density peak value of the delivering pole **106D** is a shape close to a flat shape, and that of half values, an upstream-side width is wider than a downstream-side width. Specifically, a constitution satisfying the angle difference $\Delta w \geq 0$ described in the first embodiment and the angle ratio $Wd/Wc \geq 35\%$ described in the third embodiment. Incidentally, in the case of this embodiment, different from the third embodiment, $\Delta w \geq 0$ is satisfied, and therefore, as regards the angle ratio Wd/Wc , $Wd/Wc \geq 30\%$ may only be required to be satisfied. However, it is preferable that $Wd/Wc \geq 35\%$ is satisfied.

25 In such a case of this embodiment, the magnetic flux density of the delivering pole **106E** on a side upstream of the magnetic flux density peak value of the delivering pole **106D** in a range close to the first feeding pole **105** is larger than the magnet field densities of the delivering poles in the same range in the first embodiment and the third embodiment. For that reason, compared with the first and third embodiments, the magnetic field between the first feeding pole **105** and the delivering pole **106E** is stronger and an effect of weakening the magnetic field between the first feeding pole **105** and the second feeding pole **202** is higher. For this reason, an effect of suppressing the movement of the developer between the first feeding pole **105** and the second feeding pole **202** becomes high.

[Experiment]

30 Next, an experiment in which an occurrence status of a stripe-shaped fog image (abnormal image) in the above-described constitution was checked will be described. In the experiment, by adjusting the magnetic flux density of the delivering pole **106E**, the angle difference Δw and the angle ratio Wd/Wc were changed, and images were outputted by image forming apparatuses in which delivering poles in various conditions are incorporated. Then, the occurrence status of the stripe-shaped fog image on the output image was checked.

33

Other conditions and evaluation of the experiment are the same as those of the experiment described in the first embodiment. A result of this experiment is shown in a table 6.

TABLE 6

ΔW	-3	-1	0	2	3
Wd/Wc	25%	30%	35%	41%	46%
AI*1	X	Δ	○	○	○

*1: "AI" is the abnormal image.

Constitutions of the first developing roller 30 and the second developing roller 31 in the experiment are as shown in FIG. 6. A magnetic characteristic is such that a magnetic flux density peak value of the delivering pole 106E was fixed to about 36 mT and that the angle difference Δw was changed from $-3(^{\circ})$ to $3(^{\circ})$, and at the same time, a shape of the magnetic flux density of the delivering pole 106E was changed stepwise from 25% to 46% in terms of the angle ratio Wd/Wc. The magnetic poles other than the delivering pole 106E are as shown in FIG. 7.

As is apparent from the table 6, when the angle difference Δw is $0(^{\circ})$ or more, and the angle ratio Wd/Wc is 35% or more, occurrence of the abnormal image was able to be suppressed. This is an effect such that the neighborhood of the magnetic flux density peak value of the delivering pole 106E approaches the first feeding pole 105, and thus the magnetic field between the first feeding pole 105 and the delivering pole 106E is strengthened and the magnetic field between the first feeding pole 105 and the second feeding pole 202 is weakened.

Further, even in the case of the angle difference $\Delta w=-1(^{\circ})$ and the angle ratio Wd/Wc=30%, the effect of suppressing the occurrence of the abnormal image was confirmed. However, in this condition, the magnetic field between the delivering pole 106E and the first feeding pole 105 is changed in a weakening direction due to some change in magnetic pole position by the influence of assembling tolerances of the first magnet 36 and the second magnet 37, and a variation in magnetization, so that an effect of weakening the magnetic field between the first feeding pole 105 and the second feeding pole 202 becomes low in some cases. For this reason, $\Delta w \geq 0$ may preferably be satisfied, and in this case, Wd/Wc $\geq 30\%$ may only be required to be satisfied. However, it is more preferable that the angle difference $\Delta w \geq 0$ and the angle ratio Wd/Wc $\geq 35\%$ are satisfied.

As described above, according to this embodiment, occurrence of an image defect can be suppressed. That is, in the developing device 1Y of this embodiment, the developer fed from the first feeding pole 105 to the delivering pole 106E on the first sleeve 33 and is delivered to the second sleeve 34 on the basis of the magnetic field between the delivering pole 106E and the receiving pole 201, and then is fed on the second sleeve 34 from the receiving pole 201 to the second feeding pole 202. In such a constitution, the developer is moved by the magnetic force along the magnetic field between the first feeding pole 105 and the second feeding pole 202 in some cases. On the other hand, in this embodiment, the magnetic flux density of the delivering pole 106E satisfies the angle difference $\Delta w \geq 0$ and the area ratio Wd/Wc $\geq 30\%$, preferably the angle ratio Sa/S $\geq 35\%$ as described above, so that the magnetic field between the first feeding pole 105 and the delivering pole 106E weakens the magnetic field between the first feeding pole 105 and the second feeding pole 202, and therefore movement of the developer between the first feeding pole 105 and the second

34

feeding pole 202 can be suppressed. For this reason, the occurrence of the above-described stripe-shaped fog image can be suppressed.

OTHER EMBODIMENTS

The present invention is not limited to the constitution of the above-described embodiments. For example, the image forming apparatus 100 is not limited to the MFP, but may also be a copying machine, a printer, or a facsimile machine. Further, the constitutions of the developer supplying screw 42, the developer stirring screw 43, and the developer collecting screw 44 are not particularly limited when the constitutions can convey the developer, and for example, it is possible to apply a helical blade, a paddle-like blade.

Further, in the above-described embodiments, a constitution in which the first sleeve 33 and the photosensitive drum 28Y are rotated in the same direction in mutually opposing positions and in which the second sleeve 34 and the photosensitive drum 28Y are rotated in the same direction in mutually opposing positions was described but the present invention is not limited thereto.

A constitution in which the rotation center R2 of the second developing roller 31 is disposed above the rotation center R1 of the first developing roller 30, in which the first sleeve 33 and the photosensitive drum 28Y are rotated in opposite directions in the mutually opposing positions, and in which the second sleeve 34 and the photosensitive drum 28Y are rotated in opposite directions in the mutually opposing positions may be employed. That is, in this constitution, counter development such that the photosensitive drum 28 is rotated from above to below in the vertical direction in a position where the photosensitive drum 28 opposes the first developing roller 30 is made, and counter development such that the photosensitive drum 28 is rotated from above to below in the vertical direction in a position where the photosensitive drum 28 opposes the second developing roller 31 is made. The present invention is also applicable to such a constitution. Further, in the case where three or more developing rollers are provided, the present invention is also applicable to arbitrary two developing rollers.

While the present invention has been described with reference to exemplary embodiments, it is to be understood that the invention is not limited to the disclosed exemplary embodiments. The scope of the following claims is to be accorded the broadest interpretation so as to encompass all such modifications and equivalent structures and functions.

This application claims the benefit of Japanese Patent Application No. 2023-185953 filed on Oct. 30, 2013, which is hereby incorporated by reference herein in its entirety.

What is claimed is:

1. A developing device comprising:
a developing container configured to accommodate a developer including toner and a carrier;
a first rotatable member to which the developer accommodated in the developing container is supplied and which carries and feeds the developer to a first developing position where an electrostatic latent image formed on an image bearing member is developed;
a first magnet provided non rotatably and stationarily inside the first rotatable member, wherein the first magnet includes a first developing pole provided opposed to the image bearing member in the first developing position, a delivering pole provided downstream of the first developing pole with respect to a rotational direction of the first rotatable member, and a

35

first feeding pole provided upstream of the delivering pole and adjacent to the delivering pole, with respect to the rotational direction of the first rotatable member, and having a magnetic polarity different from the delivering pole;

10 a second rotatable member provided opposed to the first rotatable member and to which the developer is delivered from the first rotatable member by a magnetic field generated by the first magnet, wherein the second rotatable member carries and feeds the developer to a second developing position where the electrostatic latent image is developed, and wherein a rotational direction of the second rotatable member in a position where on an outer peripheral surface of the second rotatable member, the second rotatable member is closest to the first rotatable member is opposite to the rotational direction of the first rotatable member in a position where on an outer peripheral surface of the first rotatable member, the first rotatable member is closest to the second rotatable member; and

15 a second magnet provided non-rotatably and stationarily inside the second rotatable member, wherein the second magnet includes a plurality of magnetic poles including a second developing pole provided opposed to the image bearing member in the second developing position, a receiving pole provided upstream of the second developing pole with respect to the rotational direction of the second rotatable member and having a magnetic polarity different from that of the delivering pole, and a second feeding pole provided downstream of the receiving pole and adjacent to the receiving pole, with 20 respect to the rotational direction of the second rotatable member, and having a magnetic polarity different from that of the receiving pole, the receiving pole being a magnetic pole, of the plurality of magnetic poles, provided closest to the delivering pole,

25 wherein in a case where

a position where on the outer peripheral surface of the first rotatable member, a magnetic flux density of the delivering pole in a normal direction relative to the outer peripheral surface of the first rotatable member is maximum is a point T,

30 of positions each where on the outer peripheral surface of the first rotatable member, the magnetic flux density of the delivering pole in the normal direction relative to the outer peripheral surface of the first rotatable member is a half value of the maximum, the position on a downstream side with respect to the rotational direction of the first rotatable member is a point Hd,

35 of the positions each where on the outer peripheral surface of the first rotatable member, the magnetic flux density of the delivering pole in the normal direction relative to the outer peripheral surface of the first rotatable member is the half value of the maximum, the position on an upstream side with respect to the rotational direction of the first rotatable member is a point Hu,

40 an angle formed by a rectilinear line L10 connecting a rotation center R1 of the first rotatable member and the point T and a rectilinear line L12 connecting the rotation center R1 and the point Hu is w1, and

5

36

an angle formed by the rectilinear line L10 and a rectilinear line L11 connecting the rotation center R1 and the point Hd is w2,

the following relationship is satisfied:

$$w1 - w2 \geq 0.$$

10 2. A developing device according to claim 1, wherein the following relationship is further satisfied:

$$w1 - w2 > 0.$$

15 3. A developing device according to claim 1, wherein the following relationship is further satisfied:

20

$$w1 - w2 \geq 2.5 \text{ degrees.}$$

25 4. A developing device according to claim 1, wherein in a graph in which an ordinate represents the magnetic flux density of the delivering pole in the normal direction relative to the outer peripheral surface of the first rotatable member and an abscissa represents an angle of the first rotatable member with respect to the rotational direction of the first rotatable member, in a case where

a rectilinear line passing through the point T and parallel to the abscissa is a rectilinear line HLt,

a rectilinear line passing through the points Hu and Hd and parallel to the abscissa is a rectilinear line HLh,

a rectilinear line passing through the point Hd and parallel to the ordinate is a rectilinear line VL11,

a rectilinear line passing through the point Hu and parallel to the ordinate is a rectilinear line VL12,

30 an area of a rectangle enclosed by the rectilinear lines VL11, VL12, HLt, and HLh is an area S, and

in a region of the rectangle, an area obtained by integrating the magnetic flux density of the delivering pole, in the normal direction relative to the outer peripheral surface of the first rotatable member, from the rectilinear line VL11 to the rectilinear line VL12 in terms of the angle of the first rotatable member with respect to the rotational direction of the first rotatable member is an area Sa,

35 the following relationship is satisfied:

$$Sa/S \geq 65\%.$$

50 5. A developing device according to claim 4, wherein the following relationship is further satisfied:

$$Sa/S \geq 70\%.$$

55

6. A developing device according to claim 1, wherein in a graph in which an ordinate represents the magnetic flux density of the delivering pole in the normal direction relative to the outer peripheral surface of the first rotatable member and an abscissa represents an angle of the first rotatable

member with respect to the rotational direction of the first rotatable member, in a case where

of positions each where the magnetic flux density of the delivering pole in the normal direction relative to the outer peripheral surface of the first rotatable member is a value which is 10% of the maximum of the magnetic flux density of the delivering pole in the normal direction relative to the outer peripheral surface of the first rotatable member, the position on an upstream side with respect to the rotational direction of the first rotatable member is a point Cu, 10

of positions each where the magnetic flux density of the delivering pole in the normal direction relative to the outer peripheral surface of the first rotatable member is a value which is 10% of the maximum of the magnetic flux density of the delivering pole in the normal direction relative to the outer peripheral surface of the first rotatable member, the position on a downstream side with respect to the rotational direction of the first rotatable member is a point Cd, 15

of positions each where the magnetic flux density of the delivering pole in the normal direction relative to the outer peripheral surface of the first rotatable member is a value which is 90% of the maximum of the magnetic flux density of the delivering pole in the normal direction relative to the outer peripheral surface of the first rotatable member, the position on an upstream side with respect to the rotational direction of the first rotatable member is a point Du, 20

of positions each where the magnetic flux density of the delivering pole in the normal direction relative to the outer peripheral surface of the first rotatable member is a value which is 90% of the maximum of the magnetic flux density of the delivering pole in the normal direction relative to the outer peripheral surface of the first rotatable member, the position on a downstream side with respect to the rotational direction of the first rotatable member is a point Dd, 25

an angle formed by a rectilinear line L11C connecting the rotation center R1 and the point Cd and a rectilinear line L12C connecting the rotation center R1 and the point Cu is Wc, and 40

an angle formed by a rectilinear line L11D connecting the rotation center R1 and the point Dd and a rectilinear line L12D connecting the rotation center R1 and the point Du is Wd, and 45

the following relationship is satisfied:

$$Wd/Wc \geq 30\%.$$

7. A developing device according to claim 6, wherein the following relationship is further satisfied:

$$Wd/Wc \geq 35\%.$$

8. A developing device comprising:

a developing container configured to accommodate a developer including toner and a carrier; a first rotatable member to which the developer accommodated in the developing container is supplied and which carries and feeds the developer to a first developing position where an electrostatic latent image formed on an image bearing member is developed; 65

a first magnet provided non-rotatably and stationarily inside the first rotatable member, wherein the first magnet includes a first developing pole provided opposed to the image bearing member in the first developing position, a delivering pole provided downstream of the first developing pole with respect to a rotational direction of the first rotatable member, and a first feeding pole provided upstream of the delivering pole and adjacent to the delivering pole, with respect to the rotational direction of the first rotatable member, and having a magnetic polarity different from the delivering pole;

a second rotatable member provided opposed to the first rotatable member and to which the developer is delivered from the first rotatable member by a magnetic field generated by the first magnet, wherein the second rotatable member carries and feeds the developer to a second developing position where the electrostatic latent image is developed, and wherein a rotational direction of the second rotatable member in a position where on an outer peripheral surface of the second rotatable member, the second rotatable member is closest to the first rotatable member is opposite to the rotational direction of the first rotatable member in a position where on an outer peripheral surface of the first rotatable member, the first rotatable member is closest to the second rotatable member; and

a second magnet provided non-rotatably and stationarily inside the second rotatable member, wherein the second magnet includes a plurality of magnetic poles including a second developing pole provided opposed to the image bearing member in the second developing position, a receiving pole provided upstream of the second developing pole with respect to the rotational direction of the second rotatable member and having a magnetic polarity different from that of the delivering pole, and a second feeding pole provided downstream of the receiving pole and adjacent to the receiving pole, with respect to the rotational direction of the second rotatable member, and having a magnetic polarity different from that of the receiving pole, the receiving pole being a magnetic pole, of the plurality of magnetic poles, provided closest to the delivering pole,

wherein in a case where

a position where on the outer peripheral surface of the first rotatable member, a magnetic flux density of the delivering pole in a normal direction relative to the outer peripheral surface of the first rotatable member is maximum is a point T,

of positions each where on the outer peripheral surface of the first rotatable member, the magnetic flux density of the delivering pole in the normal direction relative to the outer peripheral surface of the first rotatable member is a half value of the maximum, the position on a downstream side with respect to the rotational direction of the first rotatable member is a point Hd, and

of the positions each where on the outer peripheral surface of the first rotatable member, the magnetic flux density of the delivering pole in the normal direction relative to the outer peripheral surface of the first rotatable member is the half value of the maximum, the position on an upstream side with respect to the rotational direction of the first rotatable member is a point Hu, and wherein in a graph in which an ordinate represents the magnetic flux density of the delivering pole in the normal direction relative to the outer peripheral surface of the first rotatable member and an abscissa represents

39

an angle of the first rotatable member with respect to the rotational direction of the first rotatable member, in a case where
 a rectilinear line passing through the point T and parallel to the abscissa is a rectilinear line HL_t ,
 a rectilinear line passing through the points H_u and H_d and parallel to the abscissa is a rectilinear line HL_h ,
 a rectilinear line passing through the point H_d and parallel to the ordinate is a rectilinear line VL_{11} ,
 a rectilinear line passing through the point H_u and parallel to the ordinate is a rectilinear line VL_{12} ,
 an area of a rectangle enclosed by the rectilinear lines VL_{11} , VL_{12} , HL_t , and HL_h is an area S , and
 in a region of the rectangle, an area obtained by integrating the magnetic flux density of the delivering pole, in the normal direction relative to the outer peripheral surface of the first rotatable member, from the rectilinear line VL_{11} to the rectilinear line VL_{12} in terms of the angle of the first rotatable member with respect to the rotational direction of the first rotatable member is an area S_a ,
 the following relationship is satisfied:

$$S_a/S \geq 75\%.$$

9. A developing device comprising:

a developing container configured to accommodate a developer including toner and a carrier;
 a first rotatable member to which the developer accommodated in the developing container is supplied and which carries and feeds the developer to a first developing position where an electrostatic latent image formed on an image bearing member is developed;
 a first magnet provided non-rotatably and stationarily inside the first rotatable member, wherein the first magnet includes a first developing pole provided opposed to the image bearing member in the first developing position, a delivering pole provided downstream of the first developing pole with respect to a rotational direction of the first rotatable member, and a first feeding pole provided upstream of the delivering pole and adjacent to the delivering pole, with respect to the rotational direction of the first rotatable member, and having a magnetic polarity different from the delivering pole;
 a second rotatable member provided opposed to the first rotatable member and to which the developer is delivered from the first rotatable member by a magnetic field generated by the first magnet, wherein the second rotatable member carries and feeds the developer to a second developing position where the electrostatic latent image is developed, and wherein a rotational direction of the second rotatable member in a position where on an outer peripheral surface of the second rotatable member, the second rotatable member is closest to the first rotatable member is opposite to the rotational direction of the first rotatable member in a position where on an outer peripheral surface of the first rotatable member, the first rotatable member is closest to the second rotatable member; and
 a second magnet provided non-rotatably and stationarily inside the second rotatable member, wherein the second magnet includes a plurality of magnetic poles including a second developing pole provided opposed to the image bearing member in the second developing posi-

40

tion, a receiving pole provided upstream of the second developing pole with respect to the rotational direction of the second rotatable member and having a magnetic polarity different from that of the delivering pole, and a second feeding pole provided downstream of the receiving pole and adjacent to the receiving pole, with respect to the rotational direction of the second rotatable member, and having a magnetic polarity different from that of the receiving pole, the receiving pole being a magnetic pole, of the plurality of magnetic poles, provided closest to the delivering pole,

wherein in a case where

a position where on the outer peripheral surface of the first rotatable member, a magnetic flux density of the delivering pole in a normal direction relative to the outer peripheral surface of the first rotatable member is maximum is a point T ,

of positions each where on the outer peripheral surface of the first rotatable member, the magnetic flux density of the delivering pole in the normal direction relative to the outer peripheral surface of the first rotatable member is a half value of the maximum, the position on a downstream side with respect to the rotational direction of the first rotatable member is a point H_d , and

of the positions each where on the outer peripheral surface of the first rotatable member, the magnetic flux density of the delivering pole in the normal direction relative to the outer peripheral surface of the first rotatable member is the half value of the maximum, the position on an upstream side with respect to the rotational direction of the first rotatable member is point H_u , and

wherein in a graph in which an ordinate represents the magnetic flux density of the delivering pole in the normal direction relative to the outer peripheral surface of the first rotatable member and an abscissa represents an angle of the first rotatable member with respect to the rotational direction of the first rotatable member, in a case where

of positions each where the magnetic flux density of the delivering pole in the normal direction relative to the outer peripheral surface of the first rotatable member is a value which is 10% of the maximum of the magnetic flux density of the delivering pole in the normal direction relative to the outer peripheral surface of the first rotatable member, the position on an upstream side with respect to the rotational direction of the first rotatable member is a point C_u ,

of positions each where the magnetic flux density of the delivering pole in the normal direction relative to the outer peripheral surface of the first rotatable member is a value which is 10% of the maximum of the magnetic flux density of the delivering pole in the normal direction relative to the outer peripheral surface of the first rotatable member, the position on a downstream side with respect to the rotational direction of the first rotatable member is a point C_d ,

of positions each where the magnetic flux density of the delivering pole in the normal direction relative to the outer peripheral surface of the first rotatable member is a value which is 90% of the maximum of the magnetic flux density of the delivering pole in the normal direction relative to the outer peripheral surface of the first rotatable member, the position on an upstream side with respect to the rotational direction of the first rotatable member is a point C_u ,

of positions each where the magnetic flux density of the delivering pole in the normal direction relative to the

41

outer peripheral surface of the first rotatable member is a value which is 90% of the maximum of the magnetic flux density of the delivering pole in the normal direction relative to the outer peripheral surface of the first rotatable member, the position on a downstream side 5 with respect to the rotational direction of the first rotatable member is a point Cd, an angle formed by a rectilinear line L11C connecting the rotation center R1 and the point Cd and a rectilinear line L12C connecting the rotation center R1 and the 10 point Cu is Wc, and an angle formed by a rectilinear line L11D connecting the rotation center R1 and the point Dd and a rectilinear line L12D connecting the rotation center R1 and the 15 point Du is Wd, and the following relationship is satisfied:

42

$$Wd/Wc \geq 45\%.$$
